UNITED STATES PATENT OFFICE.

HUBERT S. TURNER, OF SAN DIEGO, CALIFORNIA.

TELEPHONE SYSTEM.

1,128,262.

Specification of Letters Patent. Patented Feb. 9, 1915.

Application filed June 20, 1914. Serial No. 846,228.

To all whom it may concern:

Be it known that I, HUBERT S. TURNER, a naturalized citizen of the United States, residing at San Diego, in the county of San Diego and State of California, have invented a certain new and useful Improvement in Telephone Systems, of which the following is a full, clear, concise, and exact description, reference being had to the accompanying drawings, forming a part of this specification.

My invention relates to telephone exchange systems, some features thereof being of particular service in connection with switchboard systems of the central energy multiple type, to which however, the invention is not to be restricted.

My invention has for its broad objects, first, the provision of means by which a subscriber on initiating a call to the central exchange, receives an audible signal in his telephone receiver, provided the line wires and his individual line apparatus at the central office are in operating condition; and means by which the said audible signal is stopped as soon as the operator's telephonic set is in a talking and listening position in relation to the calling subscriber, thus enabling the usual verbal question of the operator, such as, "Number please," to be dispensed with, as the cessation of the said audible signal is the subscriber's notification to state the number he desires to be connected with; second, improved means for governing the association of the said operator's telephonic set with the link connectors that are employed to unite subscribers' lines in conversation; third, the provision of means whereby it is impossible for any operator in the exchange to "listen in" on any conversation passing between two subscribers, or to connect, deliberately or accidentally, a third subscriber to the said line, so that he can "listen in" or interrupt the conversation being carried on; fourth, the provision of means whereby on testing a called for line, the operator and the calling subscriber both receive distinctive audible signals in their respective receivers, provided the called for line is being rung upon, a conversation taking place upon it, or another subscriber waiting on that line as hereinafter described, the signals for each condition being so distinct from each other as to be readily distinguished; fifth, the provision of means whereby on hearing the

"ringing" or "talking" signal or being so informed verbally by an operator, the subscriber can, on request, be so connected to the called for busy line that while he cannot overhear the conversation carried on or interrupt the same, the called for subscriber's bell will instantaneously ring as soon as the latter's telephone receiver has been replaced on its switch-hook, after the completion of a conversation, and on the removal of said telephone receiver again telephonic connection will be established between the "waiting" subscriber and the formerly busy line; sixth, the provision of means whereby the mere act of placing the calling plug attached to a link connector in the spring jack corresponding to the called for line causes a ringing current to be sent out on the said line, and means whereby if the line is in normal working condition, the operator and the calling subscriber will both hear a distinctive audible signal in their respective telephone receivers assuring them that the line called for is in a normal condition and that the subscriber's bell has been rung, and means for stopping said ringing current at the will of the operator, and thereafter automatically substituting means for re-ringing on the line at any desired interval, the said automatic rings being received in the form of an audible signal by the calling subscriber as hereinbefore described; seventh, the provision of means whereby the calling subscriber can at any time stop the ringing on the called for subscriber's line and release the same so that it will not test "busy" at any operator's position; eighth, the provision of means whereby the ringing current is instantly cut off the line and the latter connected in a talking position with the calling subscriber and a signal displayed before the operator at the central telephone exchange when the called subscriber removes his receiver from its switch-hook, whether said receiver is removed while the bell is ringing or not; ninth, the provision of improved means of operating the supervisory relays connected to the talking circuits of the respective link connectors so that the same are more efficient in operation and will respond whether ringing current is on the line or not, but only when the receiver on a called for line is removed from its switch-hook; tenth, the provision of means whereby telephonically

connected stations of calling and called lines have independent and free control of the line equipment used in initiating calls, regardless of the fact that one or more link 5 connectors employed to connect the lines may be engaged at the time with the multiple jacks associated with said lines; eleventh, the provision of means whereby the ordinary visual pilot signal displayed when 10 any line at an operator's position is initiating a call is done away with, and instead a means provided whereby the initiation of such a call sounds a distinctive audible signal in the operator's telephone receiver, the 15 said signal continuing until the call is answered, and means whereby the said signal is automatically cut off from the operator's receiver, provided she is occupied in establishing a connection between two sub- 20 scribes or talking to one of them, the said signal in such event being automatically transferred to the operator's receiver at the position at the left or right and from that position transferred without sounding to 25 another, if that operator is also busy, and if an operator is absent from a position, to automatically transfer said signal to another position, the direction of such transfer being controlled manually, and means 30 whereby a call initiated at any operator's position sounds its distinctive audible pilot signal, eliminating the distinctive transferred signal from another position; twelfth, the provision of means whereby upon the completion 35 of a conversation between two subscribers telephonically connected by means of link connectors by placing the respective receivers upon their switch-hooks, all operating and talking currents passing 40 through the link connectors are cut off, it being immaterial whether the operator removes or not said link connectors from the engaged contacts of the respective lines as far as consumption of said currents is concerned; 45 thirteenth, the provision of means whereby a "disconnect" audible signal will be heard in the operator's receiver whenever there is an idle link connector engaged with the spring contacts associated with 50 any line, so arranged that the audible signal denoting a subscriber initiating a call takes precedence over the same; fourteenth, the provision of improved means of commutation whereby the current of an alternating current ringing generator is taken off at the apex of each alternation or half cycle and sent over one limb of a divided circuit and direct current sent over another limb of the same divided circuit at 55 60 periods alternating with the former.

Other objects will be apparent from the specification.

My invention provides for more rapid handling of connections than has been afforded by other manual or semi-automatic

telephone systems, and provides a means whereby a calling subscriber is enabled to follow the manipulations and confirm the statements of the operator by means of distinctive, audible signals in his telephone receiver.

To all of the above ends the invention consists in the matters hereinafter described and more particularly pointed out in the appended claims.

The various features and advantages of my invention will more fully appear from a description of the preferred embodiment thereof, shown in the accompanying drawing which illustrates one type of a multiple 80 switchboard telephone exchange system to which my invention may be adapted, but to which type of multiple switchboard system I do not wish to be limited.

For the sake of convenience, I have shown 85 in the drawing all apparatus related to the link connectors between the two heavy black lines representing the talking circuit of the said link connector and all apparatus common to one operator's position at the 90 switchboard is shown above the top heavy line and between the dotted lines. All apparatus common to the left and right adjacent positions connected thereto, is shown at the left and right of said dotted lines, 95 and finally all apparatus common to the entire exchange is shown below the bottom heavy line excepting battery X which may be common to the entire exchange or common only to each operator's position. I 100 have shown at A B, two telephone sub-stations, each including a receiver, a^1 , a transmitter, a^2 , a switch-hook, a^3 , a call bell, a^4 , a condenser, a^5 , and primary, a^6 , and secondary a^7 of an induction coil. The elements a^2 105 and a^6 being included in a bridge of the telephone line, which bridge is open when the receiver is upon the switch-hook, a^3 , and which bridge is closed by the switch-hook, a^3 , when relieved of the weight of the 110 receiver. The elements a^4 , a^5 are included in another bridge permanently continuous with respect to alternating signaling currents, but non-continuous with respect to direct currents.

The type of sub-station outfit shown is one that I have selected for the purpose of illustrating the invention, but it is to be understood that I do not limit myself to the form of sub-station apparatus shown, for it will be obvious as the description of the invention is proceeded with, that the operation of the system does not depend upon the peculiar sub-station outfit shown.

The stations A B are connected to the exchange in the form of the invention shown by means of metallic circuits, whose limbs C D and $C^1 D^1$ are connected with the line springs or talking contacts of spring jacks E, E^1 and F, F^1 . A plurality of 130

spring jacks is shown in multiple relation with each line, the lowermost spring jack F and F¹ constituting the answering jacks, while the remaining jacks E and E¹ constitute multiple jacks. The limbs C and D also terminate in contacts on the right and left armature switches of "cut-off" or "cut-out" relay G, the limbs of each telephone line being normally connected by means of said armature switches and the contacts normally engaged thereby with a line relay H, the limb C being connected with the left hand winding and brush of commutator I and said commutator I connected to the live pole of the grounded battery K, and the limb D being connected through the right hand winding of line relay H to ground. The line relay H is actuated by the removal of the telephone receiver at a calling station from its supporting switch-hook by means of a circuit which may be traced from transmitter a², through line C, left hand armature switch and normal contact of cut-off relay G, left hand winding of line relay H to the live pole of grounded battery K by means of commutator I and its brush to ground and through the right hand winding of line relay H, right hand normal contact and armature switch of cut-off relay G, line D, Primary a⁶, switch-hook a³, back to transmitter a². As the current passing through this circuit is of a pulsating character, due to the insulating segments of commutator I, an alternating current is set up in the secondary a⁷, which is heard as an audible signal in receiver a¹ by means of a circuit which may be traced from the upper terminal of secondary a⁷, through condenser a⁸, transmitter a², switch-hook a³ and its left hand contact, receiver a¹ back to the lower terminal of secondary a⁷. This audible signal being heard by the calling subscriber assures him that his line wires are in working condition and that his line signal operating mechanism at the central exchange has operated properly. It will be noted that the brush of commutator I is also connected to the live pole of grounded battery K by means of resistance i¹ which is such that it is sufficient to prevent the complete interruption of battery current through the windings of line relay H, when the brush of commutator I is engaged with one of the insulating segments of the same, but which does not prohibit the production of a pulsating current in the circuit, including primary a⁷, owing to its resistance being much greater than that represented by commutator I and its brush. The commutators Q and Z are similarly equipped with a resistance shunt. Therefore, any circuit connected to commutator I, Q or Z, will receive a current which while pulsating in character, is not intermittent, and in this way

the relays connected to said circuit are maintained in an actuated condition.

When line relay H is actuated, as hereinbefore described, its armature switch closes a circuit which may be traced from the ground connection of said armature switch through its contact, line lamp or signal h¹, line h², primary of operator's induction coil h³ at the central operator's position, left hand winding of pilot relay L, line h⁴, and the live pole of grounded battery K, by means of commutator I and its brush back to ground, it being understood that said primary and winding are common to a group of line lamps or signals h¹ and in the case of a divided position, this group would constitute all the line signals on the left side of the position, and in the case of an undivided position it would constitute all the line signals thereof. By this means, line lamp or signal h¹ is energized by the pulsating current produced by commutator I, and at the same time an alternating current is generated in the secondary of induction coil h³ by the pulsating current flowing through the primary of the same. A circuit for this alternating current may be traced from the lower terminal of the secondary of induction coil h³, through armature switch m¹ of operator's relay M, armature switch m⁸ normally engaged with it, left hand spring switch of operator's spring jack m², sleeve m³ of operator's jack plug, operator's receiver m⁴, tip m⁵ of operator's plug, middle spring switch of operator's spring jack m², inner left hand normal contact and armature switch of operator's relay M and common return line m⁶, to the upper terminal of the secondary of induction coil h³; thus an audible signal is produced in the operator's receiver at the particular position assigned to answer calls of the line in question.

In the preferred embodiment of my invention, I take all the line lamps located with their jacks on the left hand half of each operator's position and connect same as hereinbefore described, to primary of induction coil h³, while those located on the right hand half of the same are connected to primary of induction coil h⁵, the said primary being energized and actuated in a precisely similar manner to the primary of induction coil h³, and whose secondary circuit can be traced from the lower terminal of the same through the right hand armature switch and normal contact of operator's relay M, right hand spring switch of operator's spring jack m² and receiver m⁴, and back to the upper terminal of the secondary by the same path as that used for the secondary of induction coil h³. The purpose of this division of the line lamps at each operator's position will be hereinafter described. It will thus be seen that the re-

removal of any sub-station receiver from its switch-hook displays a visual signal and at the same time causes a distinct audible signal to be heard in the operator's telephone receiver. Thus I do away with the necessity of having the operator continually on the watch for line signals or pilot signals of any kind whatsoever, and make it impossible for a line signal to actuate without notifying the operator, it being obvious that a visual signal requires a voluntary action on the part of the operator to observe the same, while on the other hand, the hearing of an audible signal is a purely automatic function.

The description so far given of an audible pilot signal is applicable only when the operator is not engaged in completing a call or talking to a subscriber. Whenever an operator is so engaged, she is obliged to insert answering plug N in a spring jack associated with the line of the calling subscriber and grasp the metallic thimble n^1 of calling plug N^1 , which is mounted on a convenient portion of the body of said plug, allowing a finger contact device m^7 connected to the winding of operator's relay M, to make electrical contact therewith. By doing this, a circuit is closed through pilot relay L and operator's relay M, which may be traced as follows: from the live pole of grounded battery K through line h^1 , right hand winding of pilot relay L; winding of operator's relay M, finger contact device m^7 , thimble n^1 of calling plug N^1 , normal contact of the middle armature switch of the three upper ones of calling relay O, winding of finger contact relay P, sleeve of answering plug N, thimble of answering jack F, left hand winding of "message register" V, winding of cut-off relay G to ground. In this manner, the windings of pilot relay L and operator's relay M are energized and pull up their respective armature switches. In this condition, should a line signal operate at the particular position whose operator is engaged in completing a connection for or conversing with another subscriber and should such line signals and jacks be one of those at the left hand side of the position, then the alternating current generated in the secondary of pilot induction coil h^3 , as hereinbefore described, would follow a circuit which can be traced as follows: from the lower terminal of secondary of pilot induction coil h^3 , spring switch m^1 and its alternate contact, right hand armature switch of pilot relay L of the position at the immediate left of the position where the signal has originated, its normal contact, right hand armature switch of operator's relay M of said position, its normal contact and right hand spring switch of operator's jack m^2 , and if the operator's plug is inserted in the said jack, to her receiver

and thence by way of the innermost left-hand armature switch of relay M, to the common return line m^6 , to the upper terminal of the secondary of pilot induction coil h^3 , in the same manner as has already been described in relation to the pilot signal at the central position. However, if this operator is also busy, then the right hand armature switch of her pilot relay L is pulled up, disengaging its normal contact and engaging its alternate one, so that the alternating, secondary current from the central position would proceed by way of said alternate contact of pilot relay L to the left hand armature switch of pilot relay L at the position to the immediate right of the central one, its normal contact, spring switch m^4 and spring switch m^8 of operator's relay M to the left hand spring switch of operator's jack m^2 , to the operator's receiver at that position and thence back to the upper terminal of secondary of induction coil h^3 of the central position by way of the common return line m^6 as has been amply described in relation to the central position. If, however, the operator at the right hand position is absent, the plug connecting her receiver is withdrawn from its jack, whereupon the left hand spring switch of operator's jack m^2 engages its contact (which engagement can only be brought about by the removal of the plug attached to the operator's receiver), the said contact being connected to the left hand switch lever of hand switch l^1 , whose contact point is connected to the left hand armature switch of pilot relay L of the next position to the right (as is clearly shown in relation to the same switch contacts at the central position). Thus the alternating current generated in the secondary of induction coil h^3 is automatically transferred to the next position and will continue to be so transferred until it reaches the first operator's position at the right where there is an operator on duty as exemplified by her receiver being plugged into its corresponding jack.

If the operator at the left hand position is absent also, her plug is withdrawn from its jack, whereupon the right hand switch spring of operator's jack m^2 at the left hand position engages its contact (which engagement can only be brought about by the removal of the plug attached to the operator's receiver, this contact being connected to the right hand switch lever of hand switch l^1 , and said switch lever being in contact with its left hand contact point and this contact point being connected to the right hand armature switch of pilot relay L at the next position to the left (as is clearly shown in relation to hand switch l^1 of the central position) the alternating current generated in the secondary of induction coil h^3 is auto-

matically transferred to the next position at the left in a similar way as described in relation to the right hand position.

It will be noted that as well as the audible pilot signals transferred from one position through an idle position (position at which there is no operator) to another, that any audible pilot signals originating at the said idle position are also transferred; for instance, when primary of induction coil h^5 of the left hand operator's position is energized in a way that has been fully explained, the alternating current generated in its secondary follows a path through the right hand armature switch of operator's relay M of the said position, its normal contact, right hand spring switch of operator's jack m^2 , and thence through the contact it is engaged with, through the right hand switch arm of hand switch l^1 , as has been fully explained in relation to a transferred audible signal from the central position. The same being true in relation to signals originating at the right hand position. However, it will be noted that the left hand winding of pilot relay L of the left hand position is connected by line h^6 to the live pole of grounded battery K , through commutator Q and its brush, and that the same winding of the said relay at the right hand position is connected by line h^7 to the same pole of the said battery through commutator Z and its brush. As these commutators, by means of the varied number of their insulating segments, produce pulsations distinct from each other in the respective primaries of the pilot induction coils, the secondaries also generate alternating current of a distinct tonal quality. In this way, an operator can distinguish from the tone produced in her receiver whether the call originates at her own position or has been transferred from the right or left sections of the positions adjacent to her own.

When an alternating current is produced in the secondary of pilot induction coil h^6 , of the central position, and the operator is busy, the audible signal is transferred in a way similar to that described in relation to pilot induction coil h^3 , only in this case, the signals are transferred to the position at the right. The circuit for this transferred signal may be traced as follows: from the lower terminal of the secondary of induction coil h^6 , through the right hand switch arm of operator's relay M , its alternate contact, left hand switch arm of pilot relay L at the right hand position, its normal contact, switch springs m^1 and m^8 of operator's relay M at said right hand position, the left hand spring switch of operator's jack m^2 and thence to the operator's receiver, or transferred to the next position if the operator's plug has been removed, as has been hereinbefore amply described. If the operator is on duty at the

right hand position and is busy when such a transfer of a signal is made, then the left hand armature switch of her pilot relay L engages its alternate contact which is connected to the right hand armature switch of pilot relay L at the position to the left of the central one, and if the operator at this left hand position is not busy, the audible signal is produced in her receiver in the manner which has already been set forth.

Thus it will be seen that each operator receives audible pilot signals from all the line signals assigned to her position, but that if she is busy the audible signals from the left hand half of said line signals will be automatically transferred to the position at the immediate left and if that operator is busy, will be transferred to the operator's position to the immediate right of the central one, and that the reverse will happen in regard to signals from the right hand half of said line signals.

My object in transferring the audible pilot signals in that way, is that it is easier for the adjacent position at the left to attend to the left hand half of the line signals of the central position than it is to attend to the right hand half as well, therefore, the signal from the latter half is sent to the position at the immediate right first and only to the left hand position in case the operator at the right hand one is busy. The reverse is naturally true in relation to the left hand position. It will be noted that the function of relay L is simply to attend to the re-transferring of these transferred signals, and that as well as being actuated by the right hand winding connected through operator's relay M , it is also actuated by the pulsating current flowing through the primaries of operator's induction coils h^3 and h^6 , from both the left and right hand line signals. Therefore, as well as re-transferring a transferred signal, when the operator is busy completing a connection or talking to a subscriber, such re-transferring will also take place should a call originate at the position to which the call has been first transferred. Thus the calls originating at each operator's position will take precedence over any transferred call. This is so arranged as it is more important for an operator to attend to the calls originating at her own position than it is to assist in attending to the calls at an adjacent position, the latter only being attended to when the operator would otherwise be idle.

Having now fully explained the operation of the line and pilot signals, I will explain the means used for completing a connection between two subscribers. Having heard the audible signal and observed the individual line signal of the calling subscriber, the operator inserts the answering

6

4128303

plug N into the answering jack F corresponding to the calling subscriber and grasps the calling plug N^1 with the finger contact device m^1 as has already been described. This finger contact device consists of an open ring of some suitable spring metal lined with an insulating substance to prevent contact of the metal portion with the finger on which it is worn. The circuit 10 through the said finger device m^1 and metallic thimble n^1 has already been traced through the winding of finger contact relay P. It will thus be seen that pilot relay L, operator's relay M and finger contact relay 15 P remain actuated as long as the operator does not remove finger contact device m^1 from the thimble n^1 of calling plug N^1 . The actuation of said finger contact relay P allows current from the live pole of 20 grounded battery K to flow by means of the brush of commutator Q, through the winding of waiting relay R, the lowermost of the three top armature switches of finger contact relay P, the contact thereof, the normal contact of spring switch r^1 controlled 25 by the top armature switch of waiting relay R, the said spring switch to the normal contact of spring switch s^1 of answering relay S, the said spring switch s^1 , winding of answering supervisory relay T, tip of answering plug N, tip spring of spring jack F, limb D, primary a^6 , switch-hook a^3 , transmitter a^2 , limb C, ring spring of spring jack F, ring contact n^2 , of answering plug 30 35 N, spring switch s^2 , of answering relay S, its normal contact, left hand contact of uppermost armature switch of actuated finger contact relay P to the other contact of same, and thence to ground, through one-half of 40 the divided winding of the split repeating coil U.

The actuation of supervisory relay T, due to the current flowing through the circuit just traced closes another circuit which may 45 be traced from ground through the winding of cut-out relay G, the left hand winding of subscriber's message register V, thimble of answering jack F, sleeve contact of answering plug N^1 , alternate contact and armature switch of actuated supervisory relay 50 T to the winding of answering relay S, where the current divides, a portion passing through said winding and supervisory lamp or signal t^1 , to the live pole of grounded battery K by means of talking commutator I and its brush; and a portion passing by 55 means of the lowermost of the two upper armature switches of answering relay S and its normal contact, the middle of the three upper armature switches of the actuated finger contact relay P and its contact, the winding of operator's message register W, switch spring w^1 and its normal contact, line h^4 , to the live pole of grounded battery 60

K, through talking commutator I and its brush.

The message registering system herein disclosed including both that of the operator and subscriber may or may not be used as desired, and forms no part of my present 70 invention. Such system, however, forms the subject of and is claimed in a divisional application hereof for improvements in "service meter systems for telephone exchanges," filed by me December 19, 1914, 75 Serial No. 878,143.

The actuation of answering relay S, due to said divided current passing through its winding, causes the uppermost of its two top armature switches to engage switch s^2 before disengaging the latter from its normal contact, thus current from the left hand winding of the grounded half of split repeating coil U replaces the current from the right hand half of the same. The 85 lowermost of the two top armature switches of the same relay, as well as breaking the electrical connection to operator's message register W, engages its two alternate contacts, the left hand one of which bridges 90 the connection between its winding and the sleeve of plug N previously made by means of the armature switch and alternate contact of supervisory relay T. My object in this is to avoid interruption of the current 95 flowing through the winding of answering relay S by an accidental or momentary disengagement of the armature switch of supervisory relay T from its alternate contact, it being well known in the art that the latter on account of its inclusion in the talking circuit, is of necessity of a very sensitive type. The right hand alternate contact of the lowermost one of the two top armature switches of answering relay S being 100 thus connected to the left hand one, closes a circuit which may be traced from the sleeve of answering plug N through the lowermost one of the three upper armature switches and its contact of calling relay O, 110 (which relay is only actuated when the called for subscriber removes his receiver from its hook, as will be hereinafter described). Through battery X, which is preferably of a very low voltage, inner 115 right hand armature switch and contact of actuated cut-out relay G, right hand winding of subscriber's message register V, the spring switch thereof and its normal contact, thimble of answering jack F and back 120 to the sleeve of answering plug N.

The actuation of answering relay S, as hereinbefore described also causes the lowermost of its two bottom armature switches to first engage spring switch s^1 and then releases same from its normal contact, thus substituting, without interruption, current 125 from the live pole of grounded battery K

through the left hand half of the split repeating coil U^1 , for the current from commutator Q , as hereinbefore described. In this way, the armature of supervisory relay T remains pulled up, though the character of current from the live pole of grounded battery K , has been changed; however, spring switch s^1 on being disengaged from its normal contact, engages its alternate one, thereby bridging the non-inductive resistance t^2 around the winding of answering supervisory relay T . I thus provide what I hold is a new and novel means of actuating the necessarily sensitive supervisory relays connected in the talking circuit of the link connectors used in a telephone system, as the said relays are first actuated by having the full force of the operating current sent through their inductive windings, the non-inductive windings being bridged across said winding after the relay armature has been pulled up; it being well known in the art that it takes but a small fraction of the operating current to hold up an armature once it has been attracted to its pole piece.

So far as has been described, the circuit of subscriber A is connected through supervisory relay T and the two left hand halves of the split repeating coil U and U^1 to the two poles of grounded battery K . When cut-out relay G operated, disengaging the line circuit of subscriber A from the windings of line relay H , the audible signal in his telephone receiver ceased, pulsating current from commutator I no longer flowing through the primary a^6 of his induction coil. This is his signal to state the number he desires to be connected with, as the operator's receiver m^4 is bridged across the right hand halves of the split repeating coil U and U^1 , simultaneously with the operations heretofore described which connected sub-station A to the left hand halves of said repeating coil. This circuit can be traced from the right hand half of split repeating coil U , right hand contact and the uppermost of the three top armature switches of actuated finger contact relay P , alternate contact of switch spring m^8 of operator's relay M , which has been actuated as hereinbefore described, the said switch spring m^8 , left hand spring of operator's spring jack m^2 , sleeve m^3 of operator's plug, operator's receiver m^4 , tip of operator's plug m^6 , middle spring of operator's spring jack m^2 , condenser m^9 , secondary of induction coil m^{10} , uppermost armature switch and contact of the three bottom ones of actuated finger contact relay P , to the right hand half of split repeating coil U^1 . By the disengagement of the innermost of the two left hand armature switches of actuated operator's relay M , and the disengagement of switch spring m^8 , from its normal contact m^1 , the audible pilot signals generated in the sec-

ondary of induction coil h^3 , as hereinbefore described, are cut off from operator's receiver m^4 , as are those generated in the right hand induction coil h^5 , by the disengagement of the right hand armature switch of operator's relay M from its normal contact. In this way, as long as an operator grasps a calling plug attached to a link connector whose answering plug is inserted in a spring jack, allowing thimble n^1 to be in contact with finger contact device m^7 , or in other words, is engaged in completing a connection between two subscribers, the audible pilot signals which normally affect her receiver are automatically cut off and transferred to the adjacent positions in a manner already described. The same applies to the transferred pilot signals through the armature contacts of pilot relay L , the latter being also actuated. It will thus be seen that the operator can listen to the calling subscriber and talk to him without interruption caused by the audible pilot signals being actuated by other subscribers initiating calls.

When operator's relay M is actuated as hereinbefore described, the various switch springs shown at the left of the same, actuate in sequence as follows: first, the innermost left hand armature switch disengages its normal contact, disconnecting the common return line m^8 to the pilot induction coils from the middle spring of operator's spring jack m^2 , tip of operator's plug m^5 and operator's receiver m^4 ; second, the outermost left hand armature switch engages its contact, closing a circuit which can be traced through it from ground, its contact, primary of operator's induction coil m^{10} , transmitter m^{11} , retardation coil m^{12} , to the live pole of grounded battery K by means of line k^1 ; third, spring switch m^8 disengages its normal contact with spring switch m^1 , and engages its alternate contact, closing the circuit through the secondary of operator's induction coil m^{10} , as hereinbefore described, said disengagement of spring switch m^1 causing the latter in its turn to disengage its normal contact and engage its alternate contact. My object in thus arranging the sequence of connections and disconnections is to evade the disagreeable click in the ear of the operator when current is sent through or cut off from the primary of an induction coil, the secondary of which is connected in series with a receiver. As arranged and described, the receiver circuit is open when current is sent through or cut off from the primary.

It will be understood that if preferred, current could be kept continuously flowing through the primary of induction coil m^{10} , transmitter m^{11} and retardation coil m^{12} , as is often done in practice, in which event relay M , could be correspondingly simplified. However, I prefer the embodiment as shown

on account of the economy in current consumption by using talking current only when actually needed by the operator.

Having been informed by the calling subscriber at sub-station A that he wishes to talk to subscriber B, for instance, and having spoken to him, if necessary, by means of the circuit just described, the operator, still grasping the thimble n^1 of calling plug 5 N¹ in such a way that finger contact device m^7 is in electrical contact with it, tests the line called for by touching the thimble of one of its multiple jacks with the tip of the plug, in a manner well known to the art. 10 (The busy tests will be described herein-after.) If the line tests "not busy," the calling plug N¹ is inserted in the multiple jack and thus a circuit is established which may be traced as follows: from the grounded terminal or cut-out relay G¹, through the winding of said relay the thimble of multiple jack E¹, sleeve n^3 of calling plug N¹, spring switch o^1 , and its normal contact, of calling relay O, winding of ringing relay Y, 15 uppermost of the two bottom armature switches and its alternate contact of actuated answering relay S, spring switch r^1 and its normal contact of waiting relay R, contact and lowermost of the three upper 20 armature switches of actuated finger contact relay P, winding of waiting relay R, to the live pole of grounded battery K by way of waiting commutator Q and its brush; in this way, both ringing relay Y and waiting relay R are actuated. When the top armature switch of waiting relay R disengages switch spring r^1 from its normal contact, it first re-makes the connection through the winding of waiting relay R by means of its own 25 connection to the same. However, at the same time that waiting relay R was pulling up its armature switches, ringing relay Y was doing the same and the winding of waiting relay R is short-circuited by a circuit which may be traced as follows: from the live pole of grounded battery K through ringing commutator Z and its brush, the lowermost of the two top armature switches of ringing relay Y and its contact, the contact and lowermost armature switch of the 30 three top ones of actuated finger contact relay P to the top armature switch of waiting relay R, the winding of which is thus short-circuited, allowing its armature switches to fall back, whereupon the current from the contact of the lowermost of the two top armature switches of ringing relay Y continues by way of the normal contact of switch spring r^1 , the contact with 35 which has been made by the said switch spring before the top armature switch of waiting relay R become disengaged. At the same time, cut-out relay G¹ is actuated, removing line relay H¹ in the same manner as described in relation to line relay H, asso-

ciated with sub-station A, thus avoiding the display of line lamp or signal h^8 , when the subscriber at sub-station B removes his receiver from its switch hook. The central office line apparatus associated with sub-station B, is shown without a message register, such as shown at V, as it is one of the purposes of my invention to connect together lines which may or may not have "message registers" for recording calls. 75 The actuation of ringing relay Y also closes a circuit which may be traced as follows: from ground through the ringing generator I¹, continuous ringing commutator K¹, alternate contact and lowermost of the three 80 bottom armature switches of actuated finger contact relay P, normal contact and bottom armature switch of the short-circuited waiting relay R, alternate contact and uppermost one of the two bottom armature 85 switches, of actuated ringing relay Y, the non-inductive resistance t^8 , tip of plug N¹, tip spring or multiple jack E¹, limb C¹ of line of sub-station B, call bell or annunciator a^4 , condenser a^5 , limb D¹, ring spring of 90 multiple jack E¹, ring contact n^4 of calling plug N¹, uppermost contact and armature switch of the two top ones of actuated ringing relay Y, and the right hand half of split repeating coil U back to ground. Thus an 95 alternating current from generator I¹ is at once impressed upon the line of sub-station B actuating the call bell or annunciator a^4 without any action on the part of the operator other than the mere insertion of the 100 calling plug N¹ in a spring jack. The ringing current returning to ground through the right hand half of the split repeating coil U, generates an alternating current in the 105 left hand half of the same and as the calling subscriber's receiver at sub-station A, and the operator's receiver are both in circuit with the two halves of said repeating coil, as has been hereinbefore described, a distinct audible signal is sounded in their 110 respective receivers assuring them that the called for subscriber's bell has been properly rung. The ringing current impressed 115 on the line as described is cut off as soon as the operator releases the thimble n^1 of calling plug N¹ from engagement with her finger contact device m^7 , because in doing so, finger contact relay P releases its armature switches, and the lowermost of the three bottom ones disengage its alternate contact 120 which is connected to continuous ringing commutator K¹ and engages its normal contact which is connected with the brush of intermittent ringing commutator L¹. The latter is connected to the brush of continuous ringing commutator K¹, but a large portion of its surface is insulated so that its brush only makes electrical contact with the exposed metallic portion thereof at certain 125 intervals. 130

All the commutators I, Q, Z, K¹ and M¹ revolve at a high speed, being preferably mounted on or geared to the armature shaft of ringing generator I¹; but commutator L¹ is so geared that it revolves at a slow speed, say one revolution every twenty seconds, so that if the exposed metallic segment thereof, adapted for engagement with its brush, is equal to one quarter of its circumference, as shown in the drawing, ringing current will be impressed on the line of subscriber B for a period of five seconds at fifteen second intervals. It will be obvious that by varying the size of the exposed metallic portion of commutator L¹ or varying its speed of rotation, any desired length of ring and silent interval between rings may be obtained. As the return path to ground through the right hand half of the split repeating coil U has not been affected by the demagnetization of finger contact relay P, the calling subscriber at sub-station A will hear in his receiver the intermittent or periodic rings in the same way as he heard the first one which has been hereinbefore described.

When the subscriber at sub-station B answers by removing his receiver from its switch-hook, limbs C¹ and D¹ are connected together, as described in relation to sub-station A, the bell or annunciator a⁴ and condenser a⁵, up to this point allowed the passage of alternating current only through limbs C¹ and D¹, but now the passage of direct current is allowed as well, and on this account a new circuit is now closed which may be traced as follows: from the live pole of grounded battery K, through commutator M¹ and its brush, lowermost one of the two bottom armature switches of ringing relay Y, switch spring y¹, winding of supervisory relay T², tip of calling plug N¹, tip spring of multiple jack E¹, limb C¹, primary a⁶, switch-hook a³, transmitter a², limb D¹, ring-spring of multiple jack E¹, ring contact n⁴ of calling plug N¹, contact and uppermost armature switch of the two top ones of ringing relay Y to the grounded terminal of grounded battery K through the right hand half of split repeating coil U. This current actuates supervisory relay T², and its armature switch closes a circuit which may be traced from the live pole of grounded battery K, through "talking commutator" I, "calling supervisory lamp" or signal t⁴, winding of calling relay O, armature switch and alternate contact of "calling supervisory" relay T², sleeve n³ of "calling" plug N¹, thimble of multiple jack E¹, winding of cut-out relay G¹ to ground. "Calling supervisory" lamp or signal t⁴ being thus displayed before the operator, she knows the calling cord is in use and that the called for subscriber has answered.

The construction of commutators K¹ and M¹ and their mode of operation is peculiar. As will be noted from the drawing, the circumference of the commutators is divided into four segments two of which are of an insulating material, each one representing in length a little over one quarter of the circumference of the commutators. Alternating with said segments are two metallic ones correspondingly less than one quarter of the circumference of the commutators. The metallic segments of commutator K¹ are connected to one of the armature brushes of alternating current ringing generator I¹, the other brush or armature terminal of same being grounded, and the metallic segment of commutator M¹ connected to the live pole of grounded battery K. Commutator K¹ is mounted preferably on the shaft of alternating current ringing generator I¹, in such a way that its brush engages the center of one of its metallic segments when the voltage, say, of the positive current delivered to said commutator by said generator is at its maximum, the brush coming in contact with the center of the other metallic segment when one half revolution of the armature of said generator has taken place, or in other words, when the voltage of the negative current delivered to said commutator is at its maximum. On the other hand, the brush of said commutator K¹, is in the center of each one of the insulating segments of said commutator at the exact time when there is no current being generated in the armature of the said generator I¹, or in other words, when the polarity of the current delivered to commutator K¹ is changing from positive to negative and vice versa. In this way I utilize for ringing purposes only that part of each cycle of alternating current, when the voltage is at its highest, utilizing the period represented by the rest of the cycle, for substituting direct current for the alternating one by means of commutator M¹, it being possible to send the intermittent current from the latter over a divided limb of the same circuit. Commutator M¹ is preferably mounted on the same shaft with I and insulated from commutator K¹ and its segments are similar thereto, but it is so mounted that when the brush of one commutator is in the center of one of its metallic segments, the brush of the other is in the center of one of its insulating segments. It will thus be seen that ringing current from commutator K¹ can never pass through non-inductive resistance t³ and winding of supervisory relay T² to ground through commutator M¹ and grounded battery K; but that, alternately, direct current is sent through the said winding and alternating current through the said non-inductive resistance. By this means, calling super-

visory relay T^2 can never be operated by the ringing current, but as soon as the receiver at sub-station B is removed from its switch-hook, there is a path for this intermittent direct current through the winding of said relay, the latter being sufficiently sensitive to attract its armature switch when energized by said intermittent direct current. This I claim is a new and novel means of commutation, a new and novel means of actuating a relay, and a new and novel means of actuating call bells or annunciations by means of alternating current.

It will be observed that means are provided whereby if the calling subscriber restores his receiver to its switch-hook before the called subscriber responds, the calling subscriber will thereby exclude the ringing generator from circuit with the called subscriber's line. This is accomplished by means of the uppermost of the two bottom armature switches of answering relay S which is connected directly to the lower terminal of the winding of ringing relay Y and which disengages its alternate and engages its normal contact when answering relay S ceases to be energized, owing to the short-circuiting of its winding by the engagement with its normal contact of armature switch of supervisory relay T, which occurs when the calling subscriber restores his receiver to its switch-hook. The winding of ringing relay Y is thus disconnected from the live pole of grounded battery K, by way of ringing commutator Z and connected to same by way of disconnect relay P^1 , whose high resistance winding does not allow sufficient current to flow through the winding of ringing relay Y and the winding of cut-out relay G^1 to maintain them in their actuated condition. In a similar way waiting relay R is deenergized if the associated link connector is in a waiting instead of a ringing condition, as will be hereinafter described.

To return to the completion of a connection when the called for subscriber answers, a circuit has already been traced through the winding of calling relay O and its actuation causes its bottom armature switch to first make contact with spring switch o^2 which turn causes spring switch o^1 to break its normal contact and engage its alternate one; the disengagement with its normal contact opens the circuit of the winding of ringing relay Y, causing the latter to release its various armature switches, the disengagement of its uppermost of the two bottom ones with its alternate contact, breaking the circuit of non-inductive resistance t^3 , with intermittent ringing commutator L^1 and bridging the former across the inductive winding of calling supervisory relay T^2 by means of its normal contact and normal contact of spring switch y^1 which is now en-

gaged with the latter. The lowermost armature switch of the two bottom ones of ringing relay Y has at the same time disconnected the live pole of grounded battery K through commutator M^1 and its brush from the winding of calling supervisory relay T^2 , but before it did so, current from said battery through the right hand half of the split repeating coil U^1 was substituted for it, said current flowing through contact and bottom armature switch of calling relay O to normal contact of spring switch y^1 where it makes contact with the latter before the same is separated from its armature switch connected to intermittent battery commutator M^1 . Simultaneously with the engagement of its contact by the bottom armature switch of calling relay O, the uppermost of the three top armature switches of the latter engages its contact thus substituting another connection to the ring contact n^4 of calling plug N^1 from the right hand half of split repeating coil U , before the same is broken by the corresponding armature switch of ringing relay Y. In this way, the current flowing through the winding of calling supervisory relay T^2 is uninterrupted notwithstanding that its current connections have been changed and as the tip and ring strands of the link connector connected to calling plug N^1 are now connected to the two halves of repeating coil U and U^1 , conversations between sub-stations A and B can now take place. When calling relay O actuated it also caused its middle armature switch of the three top ones to disengage its contact, thus breaking the circuit from finger contact thimble n^1 of calling plug N^1 to the winding of finger contact relay P. In this way, absolute secrecy in conversation between two subscribers is assured, as far as an operator is concerned, as her transmitter and receiver can only be connected to the circuit of the link connector by the actuation of finger contact relay P. The engagement of the lowermost of the three top armature switches of calling relay O with its contact, closes a circuit through a calling subscriber's message register, as has been already described. When switch o^1 of calling relay O engages its alternate contact, it allows current from sleeve n^3 of calling plug N^1 to flow direct through its winding irrespective of whether the armature switch of T^2 disengages its alternate contact, this action and the purpose thereof being the same as already described in relation to answering supervisory relay T.

Having now explained fully the functions of the apparatus to complete a call, I will proceed to describe the procedure on the completion of the same when the two receivers are placed upon their respective switch-hooks. Each sub-station has independent control of its associated link con-

- nection apparatus, it being immaterial which subscriber hangs up his receiver first; as soon as he does so his line will test "not busy" at all the multiple jacks associated 5 with his line, and if he wants another connection immediately, his individual line signal will respond, regardless of how many previously connected link connectors may still be in engagement with the spring jacks 10 associated with his line. Let us say that the subscriber at sub-station B hangs up his receiver first; then the circuit for direct current is at once broken through primary a^6 and switch-hook a^3 and calling supervisory 15 relay T^2 releases its armature switch, disengaging its alternate contact and engaging its normal one, by this action the winding of calling relay O is short-circuited, as can be seen by tracing said short-circuit from the 20 bottom terminal of the winding of relay O , through the normal contact and armature switch of calling supervisory relay T^2 to the upper terminal of said winding of calling relay O . Due to this short-circuit, said 25 relay releases its various armature switches and as spring switch o^1 disengages its alternate contact, the current from the grounded pole of grounded battery K , flowing through cut-out relay G^1 , thimble of multiple jack 30 E^1 , sleeve n^3 of calling plug N^1 and the said spring switch o^1 is cut off from the short-circuited winding of calling relay O and supervisory lamp or signal t^4 which latter thereupon resumes its normal condition. 35 The armature switches of cut-out relay G^1 also resume their normal condition, engaging their normal contacts and connecting line relay H^1 to the limbs C^1 and D^1 of sub-station B, so that line signal h^3 will 40 again respond on the removal of receiver a^1 from its switch-hook. The circuit of the tip strand of the link connector associated with calling plug N^1 through non-inductive resistance t^3 and winding of calling supervisory relay T^2 , which were multiplied together by spring switch s^1 of answering relay S , is also broken by the disengagement of the lowermost of 45 the two bottom armature switches of the same. The circuit of the ring strand of the link connector associated with answering plug N , through non-inductive resistance t^2 and winding of answering supervisory relay T , which were multiplied together by spring switch s^2 of answering relay S , is also broken by the disengagement of the lowermost of 50 the two bottom armature switches of the same. The circuit of the ring strand of the link connector associated with answering plug N , by means of ring n^2 , is broken at spring switch s^2 of the same relay. Thus it will be seen that there is no electrical connection between the tip and ring contacts of answering plug N and grounded battery K . 55 It will therefore be seen that the talking and operating strand circuits of both calling and called lines are normally open to any connection to grounded battery K . 60 The release of the armature switches of both answering and calling relays S and O establishes a circuit which may be traced as follows: from the live pole of grounded battery K , line k^1 , winding of disconnect relay P^1 , normal contact and uppermost one of 65 the two bottom armature switches of answering relay S , winding of ringing relay Y , normal contact and spring switch o^1 of calling relay O , sleeve n^3 of calling plug N^1 , thimble of multiple jack E^1 , winding of cut-out relay G^1 to ground. The winding of 70 disconnect relay P^1 is of an extremely high resistance, for instance, 30,000 ohms, so that not enough current flows through ringing relay Y and cut-out relay G^1 to operate the same. The actuation of disconnect relay P^1 causes its armature switch to engage its contact, closing a circuit which may be traced as follows: from the live pole of grounded battery K through talking commutator I 75 and its brush, line h^4 , primary of disconnect induction coil P^2 , contact and armature switch of disconnect relay P^1 to ground. The pulsating current produced by talking commutator I , as hereinbefore described, 80

passing through its primary, generates an alternating current in the secondary winding of disconnect induction coil P^2 , a circuit for which may be traced from the lower terminal of said secondary, line m^{13} , normal contact of spring switch m^1 of operator's relay M , of the central position, said spring switch m^1 , whence it is led to operator's receiver m^4 and thence to common return line m^6 which is connected to the other terminal of secondary of disconnect induction coil P^2 , in the same manner as described hereinbefore in relation to the audible pilot signals from the line lamps. The secondary of disconnect induction coil P^2 transmits a signal not as loud as that transmitted by the secondaries of pilot induction coils h^3 and h^5 , and as all three induction coils have their primaries influenced by the same pulsating current from talking commutator I , it is obvious that the operator can easily distinguish between the two, thus knowing at once whether to look at the line lamps or signals for a displayed one, or to look for a link connector engaged with spring jacks which displays no supervisory signals, also, should a line signal operate at the same time that the disconnect relay operates, the louder audible signal of the former would efface the latter. It will also be noted that as the lower terminal of the secondary of disconnect induction coil P^2 is connected to the normal contact of switch spring m^1 of operator's relay M , the audible disconnect signal conveyed through said contact is not transferred as are the audible line pilot signals.

Having now fully described a completed connection between two sub-stations and the automatic opening of the circuits through the link connectors used in making such connection when the receivers are replaced on their respective switch hooks, I will proceed to describe the "busy tests" and functions of waiting relay R which has heretofore not been described.

The described connection was made to a called for line which tested "not busy"; if on the other hand, at another position, a link connector was engaged with a multiple jack of the called for line and ringing current was being impressed thereon, then on applying the tip of calling plug N^1 to the thimble of multiple jack E^1 , as hereinbefore described, or to the metallic base of a plug, should one be already inserted in said multiple jack, a circuit would have been completed which may be traced as follows: from the grounded primary m^{14} of operator's induction coil m^{10} , middle one of the three bottom armature switches of actuated finger contact relay P and its contact, where the circuit divides; a portion proceeding by means of the normal contact of spring switch y^1 of ringing relay Y and said spring

switch, winding of calling supervisory relay T^2 to the right hand terminal of non-inductive resistance t^3 , the other portion proceeding by means of the normal contact and uppermost armature switch of the two bottom ones of ringing relay Y , non-inductive resistance t^3 , where the divided circuit is joined; tip of calling plug N^1 , thimble of multiple jack E^1 , thimble of multiple jack at the busy position, and as the link connector thereto engaged is being used for impressing ringing current on the line, the circuit would proceed through sleeve n^3 of plug N^1 , spring switch o^1 and its normal contact of calling relay O , winding of ringing relay Y , uppermost of the two bottom armature switches of answering relay S , its alternate contact, spring switch r^1 and its normal contact of waiting relay R , contact and lowermost of the two top armature switches of ringing relay Y to the live pole of grounded battery K by way of ringing commutator Z and its brush. As the said commutator furnishes a pulsating current of a nature the same as described in relation to talking commutator I , the grounded primary m^{14} of induction coil m^{10} is affected by the said pulsating current and therefore generates an alternating current in the secondary of induction coil m^{10} , which when making the test, as has been hereinbefore described, is bridged in series with operator's receiver m^4 across the halves of split repeating coil U and U^1 . Therefore, a distinct audible signal is heard by the operator in her receiver and also by the calling subscriber in his. When there are no link connectors in active use engaged with the multiple jacks of a line, then all such jacks are at the potential of the earth and in making a busy test no current passes through grounded primary m^{14} of operator's induction coil m^{10} . On the other hand, if at another operator's position a link connector was engaged with a multiple jack of the called for line and calling relay O was connected to said link connector, or in other words, the latter was in what I term the talking condition, then the circuit from the sleeve n^3 of calling plug N^1 at the "busy position" instead of leading to the live pole of grounded battery K by way of commutator Z and its brush, as hereinbefore described, would be connected thereto by way of commutator I and its brush, the circuit for which may be traced as follows: from sleeve n^3 of calling plug N^1 , spring switch o^1 and its alternate contact of calling relay O , winding of said relay, calling supervisory lamp t^4 , to the live pole of grounded battery K , by way of commutator I and its brush. By means of this circuit, an audible signal is heard in the operator's and calling subscriber's receivers, as hereinbefore described in relation to the "busy test", when

ringing current is being impressed on the called for line. As commutator I has a different number of insulating segments than commutator Z, the audible signal produced in the respective receivers is of a different tone; the variation in number of the said insulating segments of the commutators being such that these two tones can be readily distinguished from each other by both the calling subscriber and the operator. (I have shown in the drawing one insulating segment for commutator Q, two insulating segments for commutator Z and four for commutator I, but it is to be understood that the number and their ratio to each other are purely arbitrary and I do not wish to be limited to the number shown.)

Having heard the "talking" test in his receiver, or having been so informed verbally by the operator, the calling subscriber at substation A can answer "I will wait," or words to that effect, whereupon the operator would at once insert in the multiple jack E¹, the calling plug N¹ of the link connector engaged by means of answering plug N with the answering jack F associated with the line of substation A. Without any further manipulation or action on the part of the operator, the calling subscriber at sub-station A is now connected with substation B in such a way that the talking strands of the link connector connected to the lines of the latter will not be closed until the subscriber at sub-station B replaces his receiver on its switch-hook, whereupon the ringing relay Y of the link connector in the "waiting" condition will at once impress ringing current on the line and when the subscriber answers, the talking strands of the said link connector connected to his line will be closed and conversation between sub-stations A and B made possible. In case the called for line was being rung upon when the "waiting" connection was made, the talking connection will be completed to the subscriber who was first connected, and to the "waiting" subscriber only on the completion of same. This waiting connection is accomplished by the use of a relay which I term the "waiting" relay, shown at R in the drawing.

Before describing the action of waiting relay R, it will be well to state that the winding of cut-out relay G¹ is such that it equals in resistance the windings of cut-out relay G in series with message register V, so that the resistance of the grounded thimbles of all the jacks associated with the subscribers' lines is the same, whether message registers are associated with said lines or not. This resistance is such that while ringing relay Y will receive sufficient current to operate it when connected in series with waiting relay R and one of said grounded thimbles (as described in relation

to the connection with a "not busy" line) provided no other circuit is established from a thimble of a multiple jack associated with the same line, as would be the case if an active connection had been made at another 70 operator's position; if such a connection has been made first, then the division of current from the grounded thimbles through the two link connectors would not allow ringing relay Y to actuate, while at the same time, 75 it would not affect those relays associated with the link connectors which have already attracted their armature switches, or in other words, ringing relay Y operates only when receiving all the current from grounded battery K which is allowed to pass through the winding of cut-out relay G¹ or windings of cut-out relay G and message register V in series. This action can easily be obtained by an adjustment of the air 80 gap between the pole pieces and armatures of ringing relay Y, by the use of an adjustable spring, by the proper regulation of the winding of said relay, by a combination of these methods, or by other means, to any 85 particular one of which I do not wish to be limited. Therefore, when the operator inserts calling plug N¹ into a multiple jack of a "busy line," a circuit is established 90 which may be traced as follows: from the 95 grounded terminal of cut-out relay G¹, through its winding, thimble of multiple jack E¹, sleeve n³ of calling plug N¹, spring switch o¹ and normal contact of calling relay O, winding of ringing relay Y, uppermost of the two bottom armature switches 100 of actuated answering relay S and its alternate contact, spring switch r¹ and normal contact of waiting relay R, contact and lowermost one of the three top armature 105 switches of actuated finger contact relay P, winding of waiting relay R to the live pole of grounded battery K, by way of commutator Q and its brush. Waiting relay R actuates at once as the divided current from 110 the grounded thimbles of the jacks is sufficient to operate the same, but ringing relay Y does not operate, for the reason given hereinbefore. It must be remembered that, 115 (as has been described, when ringing relay Y operated, when calling plug N¹ was inserted in the multiple jack of a "not busy" line) the winding of waiting relay R was short-circuited by the lowermost one of the two top armature switches of ringing relay 120 Y, engaging its contact. Therefore, waiting relay R now remains actuated on account of ringing relay Y not actuating, and its top armature switch engaging spring switch r¹, removes the latter from its normal 125 contact, at the same time, the bottom armature switch of the said relay disengages its normal contact and engages its alternate one. As commutator Q has less insulated segments than either commutator I or Z, 130

any further busy tests made by any operator on the multiple jacks associated with the line will produce an audible signal as hereinbefore described, in relation to the "ringing" and "talking" busy tests, but distinctive to the waiting condition, as the circuit from the multiple jack thimbles will now be through both commutators Q and I or Q and Z. The busy signal current thus having a path through two of said commutators, the "waiting" busy signal is distinctive from either the "ringing" or "talking" busy signals. Therefore, the operator and another calling subscriber will be advised that some one is waiting on the line and no further connection will be made with it.

It will be seen that when the operator removes her finger contact device m^1 from contact thimble n^1 of calling plug N^1 , thus 20 breaking the connection with the winding of finger contact relay P, the only actuated relays associated with the link connector, when latter is in what I term the "waiting condition", are answering supervisory relay T, 25 answering relay S and waiting relay R, and that the tip and ring connections of calling plug N^1 which are engaged with the switch springs of multiple jack E¹ associated with the limbs of the "busy" line, are completely 30 isolated from any electrical circuit, as in order to close same, ringing relay Y or talking relay O must be operated and that the latter can only be operated by means of calling supervisory relay T², which in its turn 35 cannot be operated unless ringing relay Y has first operated. Therefore, by limiting the operation of ringing relay Y, as has been described, I provide means by which it is impossible for a calling subscriber, while 40 waiting on a "busy" line to be telephonically connected thereto, or for ringing current to be impressed thereon. It will also be seen that should the operator, by mistake, connect a calling subscriber to a busy line, 45 the action would be the same, and instead of the confusion which arises now by having three parties telephonically connected on the same line, the third party would simply be waiting for the conversation between the 50 first two parties connected to be concluded.

When the called for line on a "waiting" connection is released in a manner which has already been fully described, all the current allowed to pass the winding of cut-out relay 55 G¹, now flows through the winding of ringing relay Y of the link connector in the waiting condition, and it at once actuates, closing its respective contacts. Ringing current is at once impressed on the line of substation B, regardless of the position of the brush of intermittent ringing commutator L¹ in relation to the exposed metallic portion thereof, as the ringing circuit to latter has been cut off, due to it being connected 60 to the normal contact of the bottom armature switch of waiting relay R, and as the latter has been actuated while the link connector was in a waiting condition, it is engaged to its alternate contact which is connected direct to constant ringing commutator K¹. In this manner, instantaneously 70 with the replacing of the receiver on its switch-hook, if there is a subscriber waiting on that line, the call bell or annunciator will be operated and will continue to so operate until a subscriber answers. As the subscriber cannot have more than removed his hand from the receiver when the call bell or annunciator operates, he will naturally remove the receiver again, whereupon the 75 mechanism associated with the link connector which has been in a waiting condition, responds, and connections to the talking condition are made, as has already been described. The winding of waiting relay R 80 is not short-circuited by the closing of the lowermost of the three upper armature switches of ringing relay Y with its contact, as the circuit to the upper terminal of said winding through said contact and the lowermost contact and armature switch of the three top ones of finger contact relay P is open on account of said relay not being actuated; the alternative path for the current 85 from the said contacts through normal contact and spring switch r^1 and the top armature switch of waiting relay R being open also by the previous actuation of waiting relay R. Therefore the winding of waiting relay R can only be short-circuited and its 90 armature switches released by the actuation of ringing relay Y, when finger contact relay P is at the same time actuated, which happens only when the operator is inserting calling plug N^1 in the multiple jack and giving 95 the first ring to a called for line, as has been already described.

My only object in using waiting relay R is to furnish a means whereby, without any other manipulation on the part of an operator than is used in making a connection to a not busy line, a calling line can be connected to a busy line, and that as soon as the latter becomes "not busy", its call bell or annunciator will immediately operate and thereafter telephonic connection made with the subscriber that has been waiting. I do not, however, limit my invention in all of its aspects to the use of this relay.

Where there are two active link connectors connected to the multiple jacks associated with a line, and one of the same is released, thus closing a circuit through disconnect relay P¹, the extremely small amount of current flowing through the high resistance 120 winding of the latter does not prevent the operation of ringing relay Y of the link connector in the waiting condition.

If when the operator made the test for a busy line and the audible signal distinctive 125

to waiting commutator Q was sounded in her telephone receiver and that of the subscriber, in a manner which has been already described, and notwithstanding said signal (which would indicate that no other connection should be made to that line) should insert calling plug N¹ in the spring jack; then the current flowing from ground through cut-out relay G¹ would have three paths offered to it; to wit, the path through the link connector in the ringing or talking condition, the one through the link connector in the waiting condition and the one through the link connector by error connected to the same line, and as the adjusting means of waiting relay R is similar to that of ringing relay Y, it is so adjusted that it will not operate when such a divided path is offered the current from grounded battery K. Therefore, a link connector cannot be electrically connected to a line to which has already been connected another link connector in the waiting condition.

Having described how by means of a calling plug, telephonic connection of an operator or third party to a busy line is impossible, I will describe how the same thing is avoided if attempted by means of the answering plug. When answering plug N is inserted in a spring jack and the thimble n¹ of calling plug N¹ is grasped by finger contact device m¹, a circuit has hereinbefore been traced from ground through cut-out relay G and message register V, thimble of answering jack F, the winding of finger contact relay P, the said thimble n¹, finger contact device m¹, the windings of operator's relay M and pilot relay L to the live pole of grounded battery K. The current so derived is sufficient to energize the winding of finger contact relay P and cause same to pull up its various armature switches. However, if there is another plug either answering or calling, inserted in a spring jack multiplied on the same line, and if current from battery K is passing through the same, then the divided current at the thimbles of the spring jacks is not sufficient to operate finger contact relay P. The action and adjustment of said relay being the same as in the case of ringing relay Y when a "waiting" call is being made, as heretofore described. As no circuit is completed through the tip and ring strands of the answering cord connected to answering plug N until after finger contact relay P has actuated, it is obvious that no telephonic connection can be made with the answering plug N on a "busy line."

The two arms of hand switch l¹ at the various operators' positions are arranged to move independently of each other so that the left hand switch arm can engage its left hand contact and the right hand switch arm its right hand contact, or both engage their

left hand or right hand contacts, but the left hand switch arm cannot be made to engage its right hand contact at the same time the right hand switch arm engages its left hand contact, as in that event an audible pilot signal transferred to the right would, if that position was busy, be transferred back again to the same position it originated from. To prevent this, some such means as that shown in the drawing is used, where each of the switch arms bears an insulating buffer of the proper length to prevent the two arms from becoming close enough together to engage the two contacts mentioned. By means of the circuits already traced, it will be seen that if the hand switches of a position where the operator's plug has been withdrawn are engaging their left hand contacts, as shown in the drawing and described in relation to the left hand operator's position, then the audible pilot signals originating at that position and the transferred audible pilot signals from an adjacent position will be transferred to the next position at the left; while if the hand switches are engaging their right hand contacts, as shown in the drawing and described in relation to the right hand operator's position, the same signals would be transferred to the next position to the right; while if the left hand switch arm engages its left hand contact, and the right hand one its right hand contact, as shown in the drawing and described in relation to the central position, then the audible signals from the left hand half of the line lamp or signals would be transferred to the left and the audible signals from the right hand half, would be transferred to the right. I thus provide manually operated means for transferring the audible pilot signals from idle positions, in any way that may be deemed advisable.

I have herein shown and particularly described the preferred embodiment of my invention in order that the invention in all of its aspects may be well understood, but it will be obvious that the same can be modified and simplified in many respects without departing from the basic principles involved. For instance, by eliminating the division of the line signals at an operator's position into a left and right hand section, connected to the primaries of pilot induction coils h² and h⁵, only one induction coil would be needed, and the right hand armature switches and contacts of pilot relay L and operator's relay M could be done away with and hand switch l¹ simplified.

Disconnect relay P¹ is not an essential feature of the invention, as it is immaterial whether link connectors are left engaged with the contacts of the spring jacks or not, for in practice, the operators can, when at leisure, glance at the supervisory lamps or signals associated with said engaged link

connectors, and whenever said lamps or signals are not in an operated condition, they will remove the said link connectors from engagement with said spring jacks.

5 If preferred, instead of finger contact relay P being connected to thimble n^1 of calling plug N^1 , it could be connected to one terminal of a contact key or button, and the line leading to finger contact device m^1 to the other terminal thus doing away with both thimble and finger contact device and substituting a manually operated key or button.

I have shown but one battery, which furnishes current for the signal circuits, as well as the talking circuits. However, if preferred, the signaling circuits could be connected to a separate battery. This might be a preferred plan if the battery used for the talking circuits was such that the pulsating currents passing through commutators I , Q , Z and M^1 produced noise in the talking circuits. If a second battery was used, it could be connected to the talking battery through a low resistance retardation coil, to eliminate such pulsations, in a manner well known in the art, in relation to pole changers for ringing current. I do not wish to be limited, therefore, to the form of the invention that has been selected to illustrate it, as changes may readily be made without departing from the spirit of the invention.

It will be seen that I have provided a telephone system, including telephone lines extending to an exchange from sub-stations, jack switches in association with the telephone lines, connecting plugs attached to link connectors for engagement with said switches, a source of continuous signaling current and a source of periodic signaling current for operating the call bells or annunciators at called sub-stations normally disconnected from the calling plug, and relay mechanism individual to each link connector to control the connection of said plug to said sources of signaling current, and to remove the same under the control of apparatus at a called sub-station.

It will also be seen that I have provided a telephone system including telephone lines extending to an exchange from sub-stations, line signaling apparatus at the exchange for said telephone lines, connecting apparatus at the exchange for uniting lines in conversation, a cut-off relay governed by said connecting apparatus for preventing the presentation of the line signal of a called line or a calling line, as the case may be, and electro-magnetic mechanism operable by the apparatus at the called station, or calling station, as the case may be, independently of the apparatus of the calling station or called station, as the case may be, for removing the control of the cut-off relay from the line signal of the called line or calling

line, as the case may be, thereby permitting the called station or calling station, as the case may be, to have control of the line signal of the called line or calling line, as the case may be.

It will also be seen that I have provided a telephone exchange system, including telephone lines extending from sub-stations to an exchange, audible signals to inform the subscriber in respect to the condition of his line and line signal apparatus and the various manipulations used in making a connection, and of the operating condition of a called for line, audible signals to inform the operator that a line assigned to her position, 70 an adjacent position or an idle position assigned to her, is displaying its signal, and provided means to transfer said signals when an operator at a position is busy completing a connection between two other sub-stations, also audible signals distinctive in tone quality, or loudness, to indicate whether a called for line is being rung upon, or whether a conversation is being held upon it, or whether another subscriber is 85 waiting to be connected to it.

It will also be seen that I have provided a telephone exchange system including telephone lines extending from sub-stations to an exchange, electro-magnetic mechanism 90 operable by the apparatus at the called station, whether a calling sub-station can be connected to a sub-station already telephonically connected to another in such a way that the calling sub-station will not be telephonically connected to the one already so connected until the telephonic connection therewith has first been broken, as well as various other features which together with the foregoing will be more fully pointed out 105 in the claims.

The talking strand circuit of this system is the circuit which includes the tip and ring strands of the link connectors and the circuit connections of these strands to the 110 windings of the repeating coil or to circuits controlled by the relays, individual to each link connector and involved in establishing a connection between sub-stations through said link connector, and the operating 115 strand circuit is the circuit which includes the sleeve strand of the link connectors and the circuit connections of this strand to said relays, as distinguished from a strand circuit, for example, such as that of 120 the disconnect relay which is not individual to said link connectors.

Having thus described my invention, I claim as new, and desire to secure by Letters Patent the following:

1. A telephone exchange system, including telephone lines extending from sub-stations to an exchange, a visual line signal at said exchange for each of said lines, a source of variable current, a circuit controlled by 130

apparatus at a calling sub-station to impress upon its telephone line a variable current from said source to cause said visual line signal to be energized and at the same time 5 sound an audible signal in the telephone receiver at said calling sub-station, indicating that said sub-station's line wires and signal means at the exchange are in operating condition, and means under the control of an 10 operator to discontinue said audible signal, indicating that said operator is ready to receive a communication from said sub-station.

2. A telephone exchange system, including 15 telephone lines extending from sub-stations to an exchange having a line relay and a visual line signal individual to each sub-station, an operating circuit for each such signal, said circuit including means controlled by the line relay individual thereto, to impress thereon a continuous pulsating current, and a circuit in branch relation to each of said visual line signal circuits and including a winding of its corresponding 20 line relay and the primary of an induction coil associated with the sub-station apparatus of a calling line, whereby a current will traverse said line relay which will hold its armature contact closed and at the same 25 time sound an audible signal in the telephone receiver at the calling sub-station by means of the connection of said telephone receiver to the secondary of said induction coil, a cut-out relay, and means under the 30 control of an operator and including the cut-out relay associated with the calling line to open said audible signal circuit.

3. A telephone exchange system, including 35 telephone lines extending from sub-stations to an exchange having a visual line signal individual to each sub-station, an operator's telephone set, and means common respectively to groups of said line signals to sound an audible signal in the receiver 40 of said operator's telephone set simultaneously with the operation of any visual line signal in a corresponding group.

4. A telephone exchange system, including 45 telephone lines extending from sub-stations to an exchange having a visual line signal individual to each sub-station, a telephone receiver normally associated with a group of said signals, and means under the control of apparatus at a calling sub-station 50 to send a continuous pulsating current through said visual line signal and thereby impress an alternating current on the operating circuit of said receiver.

5. A telephone exchange system, including 55 telephone lines extending from sub-stations to an exchange having a visual line signal individual to each sub-station, a line relay individual to each of said signals for controlling the same, an operator's telephone set, means controlled by said line 60

relays to impress a continuous pulsating current on the operating circuit of corresponding visual line signals, and means also controlled by said line relay to impress an alternating current on the operating circuit of an operator's telephone receiver. 70

6. A telephone exchange system, including 75 telephone lines extending from sub-stations to an exchange having a visual line signal associated with the line of each of said sub-stations, an operating circuit for each of said visual line signals including a source of variable current, a telephone receiver associated with a group of said visual line signals, whereby said variable current 80 is caused to produce an audible signal in said receiver, on the operation of one or more of said visual line signals in said group.

7. A telephone exchange system, including 85 telephone lines extending from sub-stations to an exchange having a visual line signal and line relay individual to each sub-station, an operator's telephone set, an operating circuit for each of said visual line 90 signals, controlled by the line relay individual thereto and including a source of current, commutating means for impressing said current on said circuit in continuous pulsations, the primary of an induction coil, 95 and a circuit including the secondary of said induction coil adapted to sound an audible pilot signal in an operator's telephone receiver.

8. A telephone exchange system, including 100 telephone lines extending from sub-stations to an exchange having a visual line signal individual to each sub-station, a telephone receiver for each operator's position at said exchange, a pilot relay for each such 105 position, a source of variable current, an operating circuit for each of said visual line signals including said source and a winding of said pilot relay, an operator's relay for each of said positions, a circuit controlled 110 by said operator's relay and including said telephone receiver, whereby said variable current will sound an audible pilot signal in said telephone receiver, on the operation of one or more of said visual line signals at 115 a corresponding position.

9. A telephone exchange system including 120 telephone lines extending from sub-stations to an exchange having a visual line signal individual to each sub-station, a line relay individual to each sub-station, an operator's telephone set for each operator's position, a pilot relay individual to each operator's position, an operating circuit for each of said visual line signals and controlled by the line relay of the corresponding sub-station, each of said circuits including a source of current, means to impress said current thereon in continuous pulsations, the primary of an induction coil, and 125 130

3 a winding of said pilot relay; an operator's relay individual to each operator's position, a circuit controlled by said operator's relay and including the secondary of said induction coil and an operator's telephone receiver, whereby the alternating current set up in said secondary will sound an audible pilot signal in said operator's telephone receiver.

10 10. A telephone exchange system, including telephone lines extending from sub-stations to an exchange having a visual line signal individual to each sub-station, a line relay individual to each sub-station, an operator's telephone set for each operator's position, a pilot relay individual to each operator's position, an operating circuit for each of said visual line signals and controlled by the line relay of the corresponding sub-station, each of said circuits including a source of current, means to impress said current thereon in continuous pulsations, the primary of an induction coil and a winding of said pilot relay; an operator's relay individual to each operator's position, a circuit controlled by said operator's relay and including the secondary of said induction coil and an operator's telephone receiver, whereby the alternating current set up in said secondary will sound an audible signal in said operator's telephone receiver, and a circuit in branch relation to the operating circuit of said visual line signal and including the winding of said line relay and a telephone receiver at a calling sub-station, whereby on the operation of a visual line signal at the exchange an audible signal will be sounded in said telephone receiver at said calling sub-station, indicating the operation of said signal.

11 11. A telephone exchange system, including telephone lines extending from sub-stations to an exchange having a visual line signal individual to each sub-station, a telephone receiver for each operator's position, means common respectively to groups of said visual line signals to sound an audible pilot signal in said receiver distinct in character from the audible pilot signal sounded in said telephone receivers at adjacent operators' positions, and means under the control of apparatus at a calling sub-station to operate its individual visual line signal and the particular audible pilot signal assigned to the operator's position where said visual line signal is installed.

12 12. A telephone exchange system, including telephone lines extending from sub-stations to an exchange having means for connecting sub-stations, visual line signals for said sub-stations, an operator's telephone set at each operator's position, means common respectively to groups of said visual line signals to sound an audible pilot signal in an operator's telephone receiver simultaneously

with the operation of any of said visual line signals in a corresponding group, and means operative when a given operator is engaged in communicating with a calling sub-station or completing a connection therefor to automatically transfer said audible pilot signal to an operator's telephone receiver at an adjacent position.

13 13. A telephone exchange system, including telephone lines extending from sub-stations to an exchange having means for connecting sub-stations, a visual line signal individual to each sub-station, an operator's telephone set at each operator's position, means common respectively to groups of said visual line signals to sound an audible pilot signal in an operator's telephone receiver simultaneously with the operation of any of said visual line signals in a corresponding group, means operative when a given operator is engaged in communicating with a calling sub-station or completing a connection therefor to automatically transfer said audible pilot signal to an operator's telephone receiver at an adjacent position, and means operating on the receipt of any pilot signal originating in an operator's position to automatically cut off the transfer to that position of said signals from an adjacent position.

14 14. A telephone exchange system, including telephone lines extending from sub-stations to an exchange having means for connecting sub-stations, a visual line signal individual to each sub-station, an operator's telephone set at each operator's position, means common respectively to groups of said visual line signals to sound an audible pilot signal in an operator's telephone receiver simultaneously with the operation of any of said visual line signals in a corresponding group, and means operative when a given operator is engaged in communicating with a calling sub-station or completing a connection therefor to automatically transfer said audible pilot signal to an operator's telephone receiver at an adjacent position and if said second operator is occupied in the same way, to re-transfer said audible pilot signal to another operator's position adjacent to the first.

15 15. A telephone exchange system, including telephone lines extending from sub-stations to an exchange having means for connecting sub-stations, a visual line signal individual to each sub-station, an operator's telephone set at each operator's position, means common respectively to groups of said visual line signals to sound an audible pilot signal in an operator's telephone receiver simultaneously with the operation of any of said visual line signals in a corresponding group, means operative when a given operator is engaged in communicating with a calling sub-station or completing a connection

tion therefor to automatically transfer said audible pilot signal to an operator's telephone receiver at an adjacent position and if said second operator is occupied in the same way, to re-transfer said audible pilot signal to another operator's position adjacent to the first, and means operating on the receipt of any pilot signal originating in an operator's position to automatically cut off the transfer to that position of said signals from an adjacent position and to automatically re-transfer them to another position.

16. A telephone exchange system, including telephone lines extending from sub-stations to an exchange having a switchboard provided with a visual line signal individual to each sub-station, an operator's telephone set at each operator's position provided with a jack plug adapted to engage a spring jack at each of said positions, and means common respectively to groups of said line signals to sound an audible pilot signal in an operator's telephone receiver simultaneously with the operation of any of said visual line signals in a corresponding group, and means operative when a given operator is engaged in communicating with a calling sub-station or completing a connection therefor to automatically transfer said audible pilot signal to an operator's telephone receiver at an adjacent position and if said second operator is occupied in the same way, to re-transfer said audible pilot signal to an operator's telephone receiver at another operator's position adjacent to the first, and if any of said operator's telephone receiver jack plugs are withdrawn from their respective spring jacks, to transfer said signal to the next adjacent operator whose said jack plug is engaged with its spring jack, manually operated switches at each operator's position for determining the direction of said transfer from said position in which said jack plug is withdrawn from its spring jack, and means whereby the signal transferred to either operator's position adjacent to the one first receiving it is of a different character from the audible pilot signals originating in said adjacent operator's position, and means operating on the receipt of any pilot signal originating in an operator's position to automatically cut off the transfer to that position of said signal from an adjacent position and to automatically re-transfer them to another position.

17. A telephone exchange system, including telephone lines extending from sub-stations to an exchange having a switchboard provided with a visual line signal individual to each sub-station, an operator's telephone set at each operator's position provided with a jack plug adapted to engage a spring jack at each of said positions, and means common respectively to groups of said line signals to sound an audible pilot signal in an operator's telephone receiver simultaneously with the operation of any of said visual line signals in a corresponding group, and means operative when a given

operator is engaged in communicating with a calling sub-station or completing a connection therefor to automatically transfer said audible pilot signal to an operator's telephone receiver at an adjacent position and if said second operator is occupied in the same way, to re-transfer said audible pilot signal to another operator's position adjacent to the first, and if any of said operator's telephone receiver jack plugs are withdrawn from their respective spring jacks, to transfer said signal to the next adjacent operator whose said jack plug is engaged with its spring jack, manually operated switches at each operator's position for determining the direction of said transfer from said position in which said jack plug is withdrawn from its spring jack, and means whereby the signal transferred to either operator's position adjacent to the one first receiving it is of a different character from the audible pilot signals originating in said adjacent operator's position, and means operating on the receipt of any pilot signal originating in an operator's position to automatically cut off the transfer to that position of said signal from an adjacent position and to automatically re-transfer them to another position.

18. A telephone system comprising in combination with sub-station lines an exchange switchboard therefor having a plurality of operators' positions, means initiated at a sub-station for producing a pilot signal at an operator's position, and means individual to said position and controlled by the operator thereat to cause said sub-station means to instantly produce said pilot signal at another of said operators' positions, and automatic switching means at said positions, whereby on the disconnection of an operator's telephone receiver from its operative connection, said pilot signals are instantly produced at another operator's position.

19. A telephone system comprising in combination with sub-station lines an exchange switchboard therefor having a plurality of operators' positions, means initiated at a sub-station for producing a pilot signal at an operator's position, means individual to said position and controlled by the operator thereat to cause said sub-station means to instantly produce said pilot signal at another of said operators' positions, automatic switching means at said positions, whereby on the disconnection of an operator's telephone receiver from its operative connection, said pilot signals are instantly produced at another operator's position, and manually operated switches at said positions for selecting the position at which said pilot signals shall be produced.

20. A telephone exchange system, includ-

ing telephone lines extending from sub-stations to an exchange having a switch-board provided with a plurality of operators' positions, means initiated at a calling sub-station for producing a pilot signal at a section of said switchboard in which its line terminates, an operator's relay individual to each operator's position, means controlled by said operator's relay at a given operator's position to automatically transfer the pilot signals originating in the position of an operator engaged in completing a connection, to an adjacent operator's position, and a pilot relay controlled by the circuit of said pilot signal and also by the circuit of said operator's relay, adapted to automatically re-transfer said transferred pilot signals to another operator's position.

21. A telephone system comprising in combination with sub-station lines an exchange switchboard therefor having a plurality of operators' positions, means initiated at a calling sub-station for producing a pilot signal at a section of said board in which its line terminates, link connectors terminating in answering and calling plugs, each such calling plug provided with a thimble contact adapted to be grasped by an operator, a relay individual to each link connector and having a winding one terminal of which is connected to the sleeve contact of the answering plug of its corresponding link connector and the other terminal connected to the thimble contact of its corresponding calling plug, a contact adapted to be worn on the finger of an operator and to engage said thimble contact of a calling plug when said operator grasps said plug to make a connection therewith, an operator's relay individual to each operator's position and having a winding in circuit with said contacts which circuit is adapted to be completed by said contacts, and means controlled by said operator's relay at a given operator's position, and operative on the engagement of the operator's finger contact with said thimble contact of the calling plug selected, to automatically transfer the pilot signals originating in the position of an operator engaged in completing a connection, to an adjacent operator's position.

22. A telephone exchange system, including telephone lines extending from sub-stations to a multiple switchboard having a visual line signal individual to each sub-station, a plurality of operators' positions for said switchboard each position having two groups of said line signals assigned to it, a pilot signal individual to each position and operated on the energization of any of said line signals pertaining to either of said groups, and operator controlled means whereby a pilot signal is operated at an adjacent operator's position on the energiza-

tion of any of said line signals pertaining to one of said groups and a pilot signal operated at another adjacent operator's position on the energization of any of said line signals pertaining to the other group.

23. A telephone exchange system, including telephone lines extending from sub-stations to a multiple switchboard having a visual line signal individual to each sub-station, a plurality of operators' positions for said switchboard each position having two groups of said line signals assigned to it, a pilot signal individual to each operator's position and operated on the energization of any of said line signals pertaining to either of said groups, and operator controlled means whereby a pilot signal is operated at an adjacent operator's position on the energization of any of said line signals pertaining to one of said groups and a pilot signal operated at another adjacent operator's position on the energization of any of said line signals pertaining to the other group, and means operated on the energization of one or more of said visual line signals pertaining to either of said groups at an operator's position and also on the operation of said operator controlled means, whereby said second and third mentioned pilot signals are operated at still other separate operators' positions.

24. A telephone exchange system, including telephone lines extending from sub-stations to an exchange having link connectors for connecting said sub-stations and comprising normally open talking and operating strand circuits individual to the respective link connectors, adapted to be closed by means under the control of an operator when establishing a connection between said sub-stations and opened during an established connection by means under the control of apparatus at connected sub-stations.

25. A telephone exchange system, including telephone lines extending from sub-stations to an exchange, link connectors for connecting said sub-stations and comprising normally open separate talking and operating strand circuits individual to the respective link connectors for calling and called sub-stations, adapted to be closed by means under the control of an operator when establishing a connection between said sub-stations, said strand circuits connected to one sub-station adapted to be opened by means under the control of apparatus at said sub-station independent of said strand circuits connected to the other sub-station which are adapted to be opened by means of apparatus under the control of said other sub-station.

26. A telephone exchange system, including telephone lines extending from sub-stations to an exchange, a link connector to connect said sub-stations and comprising

normally open and separate talking and operating strand circuits individual to the respective link connectors for calling and called lines, said strand circuits adapted to be closed 5 by means under the control of an operator, a high resistance disconnect pilot circuit, an answering relay, a ringing relay and a calling relay associated with said link connector, means including the deenergization of said 10 relays whereby all the circuits closed by means of the operating strands of said link connector during an established connection therewith are opened excepting said high resistance disconnect pilot circuit which is 15 closed thereby.

27. A telephone exchange system, including telephone lines extending from sub-stations to an exchange, link connectors to connect said sub-stations and including normally open separate talking and operating strand circuits individual to the respective link connectors for calling and called sub-stations, operator controlled means for closing 20 said strand circuits of a link connector pertaining to a calling sub-station, and means for maintaining closed said strand circuits and thereby closing the talking and operating strand circuits in said link connector pertaining to a called sub-station, provided the strand circuits of said link connector pertaining to a calling sub-station have been connected to the line of a calling 25 sub-station.

28. A telephone exchange system, including telephone lines extending from sub-stations to an exchange, link connectors to connect said sub-stations and including normally open separate talking and operating strand circuits individual to the respective link connectors for calling and called sub-stations and contacts associated with said strand circuits adapted to engage jack contacts, operator controlled electro-magnetic means for closing said strand circuits of 30 said link connectors pertaining to a calling line and electro-magnetic means under the control of a calling sub-station for maintaining closed said strand circuits and thereby closing the talking and operating strand 35 circuits in said link connector pertaining to a called line, provided the contacts of said link connector pertaining to a calling line are in engagement with the contacts of a jack associated with the line of a calling 40 sub-station.

29. A telephone exchange system, including telephone lines extending from sub-stations to an exchange, link connectors to connect said sub-stations and including normally open separate talking and operating strand circuits individual to the respective link connectors for calling and called sub-stations, operator controlled electro-magnetic means for closing the talking and operating strand 45 circuits of said link connector

nectors pertaining to a called sub-station and impressing signaling current on the line of said called sub-station, and means for maintaining closed said strand circuits connected to the line of a called sub-station, 70 provided that said talking and operating strand circuits of said link connector pertaining to a calling sub-station are connected to the line of a calling sub-station, whereby a called sub-station cannot be signaled unless a calling sub-station is telephonically associated with the same link connector. 75

30. A telephone exchange system, including telephone lines extending from sub-stations to an exchange, link connectors to connect said sub-stations and including normally open separate talking and operating strand circuits individual to the respective link connectors for calling and called sub-stations, a circuit including means for sounding an audible line pilot signal in an operator's telephone receiver, operator controlled electro-magnetic means including a link connector for transferring said operator's receiver from operative relation to said audible line pilot signal to operative relation to the circuit of a calling sub-station, and means operated independently of the operator and dependent on the called sub-station apparatus for prohibiting said transfer, whereby an operator is prevented from listening to conversations passing through 90 said link connector. 95

31. A telephone exchange system, including telephone lines extending from sub-stations to an exchange, link connectors to connect said sub-stations and comprising normally open separate talking and operating strand circuits individual to the respective link connectors for calling and called sub-stations, operator controlled means for closing said strand circuits, an answering relay associated with said calling sub-station strand circuits, the energization of said relay holding said strand circuits closed after the removal of said closing means, means under the control of apparatus at the calling sub-station independent of apparatus at the called sub-station during an established 100 connection by one of said link connectors, for deenergizing said relay thereby restoring said strand circuits connected to said calling sub-station to their normal open condition, without opening the strand circuits 110 connected to a called sub-station. 120

32. A telephone exchange system, including telephone lines extending from sub-stations to an exchange, link connectors to connect said sub-stations and comprising normally open separate talking and operating strand circuits individual to the respective link connectors for calling and called sub-stations, operator controlled means for closing said strand circuits, a ringing relay and 125 130

5 a calling relay associated with said called sub-station strand circuits, the energization of said ringing relay maintaining said strand circuits closed after the removal of said closing means, means under the control of apparatus at the called sub-station to energize said calling relay, thereby deenergizing said ringing relay, and thereafter, independent of apparatus at the calling sub-station during an established connection by one of said link connectors, deenergizing said calling relay thereby restoring said strand circuits connected to said called sub-station to their normal open condition, without opening the strand circuits connected to a calling sub-station.

20 33. A telephone exchange system, including telephone lines extending from sub-stations to an exchange, link connectors to connect said sub-stations and comprising normally open separate talking and operating strand circuits individual to the respective link connectors for calling and called sub-stations, operator controlled means for closing said strand circuits, an answering relay associated with said calling sub-station strand circuits and a ringing relay associated with said called sub-station strand circuits, the energization of said relays 25 maintaining said calling and called sub-station strand circuits closed after the removal of said closing means, means under the control of apparatus at the calling sub-station independent of apparatus at the called sub-station during an established connection by one of said link connectors, for deenergizing said relays thereby restoring said strand circuits connected to both calling and called sub-stations to their normal open condition.

30 34. A telephone exchange system, including telephone lines extending from sub-stations to an exchange, link connectors for connecting said sub-stations and comprising separate talking strand circuits for calling and called lines, said circuits normally disconnected from each other and from any source of electrical energy, and connected to each other and to said source of electrical energy by manually controlled exchange 35 means only, during an established connection between sub-stations, and means under the control of apparatus at the calling and called sub-stations, during an established connection by one of said link connectors, by 40 which either sub-station independent of the other can restore the talking strand circuit connected to its line to its normal condition, thus telephonically disconnecting said sub-stations from each other.

45 35. A telephone exchange system, including telephone lines extending from sub-stations to an exchange, link connectors to connect said sub-stations and comprising separate talking and operating strand circuits individual to the respective link connectors for

50 calling and called lines, and means under the control of apparatus at said sub-stations during an established connection by one of said link connectors by which either sub-station independent of the other can automatically open said strand circuits connected to its line. 70

36. A telephone exchange system, including telephone lines extending from sub-stations to an exchange, link connectors to connect said sub-stations and comprising separate talking and operating strand circuits individual to the respective link connectors for calling and called sub-stations, and sub-station controlled electro-magnetic means whereby during an established connection by one of said link connectors either subscriber at said sub-stations independent of the other can open said link connector strand circuits connected to his line upon the replacing of his telephone receiver on its switch-hook. 75

37. A telephone exchange system, including telephone lines extending from sub-stations to an exchange, link connectors to connect said sub-stations and comprising separate talking and operating strand circuits individual to the respective link connectors for calling and called lines, and means under the control of apparatus at said sub-stations during an established connection by one of said link connectors whereby either sub-station independent of the other can automatically open said link connector strand circuits connected to its line, said means including a relay controlled by the talking strand circuit and whose armature switch controls the operating strand circuit, and a relay whose winding is in said operating strand circuit, and which relay controls said talking strand circuit. 80

38. A telephone exchange system, including telephone lines extending from sub-stations to an exchange, link connectors to connect said sub-stations and comprising separate talking and operating strand circuits individual to the respective link connectors for calling and called lines, a disconnect signal circuit associated with said link connectors during an established connection therewith and closed by the opening of said talking and operating strand circuits under the combined control of both calling and called sub-stations. 85

39. A telephone exchange system, including telephone lines extending from sub-stations to an exchange, link connectors to connect said sub-stations and comprising separate talking and operating strand circuits individual to the respective link connectors for calling and called lines, a disconnect audible signal circuit including an operator's telephone receiver when said operator is disengaged, said circuit associated with said link connectors during an established connection therewith and closed by the 90

opening of said talking and operating strand circuits under the combined control of both calling and called sub-stations.

40. A telephone exchange system, including telephone lines extending from sub-stations to an exchange, link connectors to connect said sub-stations and comprising separate talking and operating strand circuits individual to the respective link connectors 10 for calling and called lines, means under the control of the calling and called sub-stations to open the talking and operating strand circuits of said link connectors connected to their lines, a disconnect signal circuit associated with said link connectors during an established connection therewith, said disconnect circuit including a high resistance and closed when said link connector strand circuits of both calling and called lines are 15 opened, and relays in series with said circuit rendered inoperative by said resistance when said link connector strand circuits of both calling and called lines are so opened.

41. A telephone exchange system, including telephone lines extending from sub-stations to an exchange, link connectors to connect said sub-stations and comprising separate talking and operating strand circuits individual to the respective link connectors 25 for calling and called lines, means under the control of apparatus at the calling and called sub-stations to open the talking and operating strand circuits of said link connectors connected to their lines, a high resistance 30 circuit including the magnetic winding of a disconnect relay, and a disconnect signal operated by said relay when said link connector strand circuits of both calling and called sub-stations are so opened.

40. 42. A telephone exchange system, including telephone lines extending from sub-stations to an exchange, link connectors to connect said sub-stations and comprising separate talking and operating strand circuits 45 individual to the respective link connectors for calling and called lines, means under the control of apparatus at the calling and called sub-stations to open the talking and operating strand circuits of said link connectors connected to their lines, a high resistance 50 circuit including the magnetic winding of a disconnect relay, and a disconnect signal circuit operatively associated with an operator's telephone receiver when said operator 55 is disengaged, said circuit having means controlled by said disconnect relay to sound an audible signal in said operator's telephone receiver when said link connector strand circuits of both calling and called 60 sub-stations are so opened.

43. A telephone exchange system, including telephone lines extending from sub-stations to an exchange, link connectors to connect said sub-station and comprising separate talking and operating strand circuits 65

individual to the respective link connectors for calling and called lines, means under the control of the calling and called sub-stations to open the talking and operating strand circuits of said link connectors connected to their lines, a disconnect signal circuit associated with said link connectors during an established connection therewith, said disconnect circuit including a high resistance and closed when said link connector strand circuits of both calling and called lines are so opened.

44. A telephone exchange system, including telephone lines extending from sub-stations to an exchange, link connectors to connect said sub-stations and comprising separate talking and operating strand circuits individual to the respective link connectors for calling and called lines, means under the control of apparatus at the calling and called sub-stations to open the talking and operating strand circuits of said link connectors connected to their lines, a disconnect signal circuit associated with said link connectors during an established connection therewith, said disconnect circuit including a high resistance and closed when said link connector strand circuits of both calling and called lines are opened, and the winding of a disconnect relay, the winding of a ringing relay individual to each link connector and the winding of a cut-out relay individual to each called line, said relays being rendered inoperative by said resistance when said link connector strand circuits of both calling and called lines are so opened.

45. A telephone exchange system, including telephone lines extending from sub-stations to a multiple switchboard, link connectors to connect called sub-stations to calling ones, a testing contact associated with a strand of each of said link connectors, a test system which includes operating contacts associated with said lines and adapted to engage said testing contact when a test is made, a test circuit including different sources of variable current and said testing and operating contacts, means including a connection from one or more of said sources of variable current to said operating contacts, depending on the operating condition of a busy line, and a telephone receiver associated during a test with said test circuit, whereby said variable current 130

is caused to produce audible busy signals in said receiver distinctive in character to various operating conditions of said busy line.

46. A telephone exchange system, including telephone lines extending from sub-stations to an exchange, link connectors to connect called sub-stations to calling ones, a testing contact associated with a strand of each of said link connectors, a test system which includes operating contacts associated with said lines and adapted to engage said testing contact when a test is made, a test circuit including different sources of variable current and said testing and operating contacts, means including a connection from one or more of said sources of variable current to said operating contacts, depending on the operating condition of a busy line, and an operator's and a calling sub-station's telephone receiver associated during a test with said test circuit, whereby said variable current is caused to produce audible busy signals in said telephone receivers distinctive in character to various operating conditions of said busy line.

47. A telephone exchange system, including telephone lines extending from sub-stations to a multiple switchboard, link connectors to connect said sub-stations and comprising normally open separate talking and operating strand circuits individual to the respective link connectors for calling and called lines, means controlled by operators only for closing said strand circuits, a test system, and means under the control of apparatus at one sub-station during an established connection by one of said link connectors to eliminate said test system from the line of said sub-station by opening said talking and operating strand circuits of said link connector connected to the line of said sub-station.

48. A telephone exchange system, including telephone lines extending from sub-stations to a multiple switchboard, link connectors comprising normally open separate talking and operating strand circuits individual to the respective link connectors for calling and called lines to connect said sub-stations, means controlled by operators only for closing said strand circuits, a test system for producing signals distinctive to various conditions of a tested line, and means under the control of apparatus at one sub-station during an established connection by one of said link connectors to eliminate said test system from its line during the time said established connection continues, by opening said talking and operating strand circuits of said link connector connected to the line of said sub-station, independent of the apparatus at the other sub-station.

49. A telephone exchange system, including telephone lines extending from sub-stations to a multiple switchboard and comprising

normally open separate talking and operating strand circuits for calling and called lines, means controlled by operators only for closing said strand circuits, a test system, and means under the control of apparatus at a calling sub-station during an established connection by one of said link connectors and operative previous to the response of a called sub-station to its calling signal, to eliminate said test system from the test contacts associated with both calling and called lines, irrespective of the engagement of the contacts of said link connector with the jack contacts of the calling and called lines, by opening said talking and operating strand circuits of said link connector connected to the lines of both calling and called sub-stations.

50. A telephone exchange system, including telephone lines extending from sub-stations to a multiple switchboard, link connectors to connect said sub-stations and comprising normally open separate talking and operating strand circuits individual to the respective link connectors for calling and called lines, means controlled by operators only for closing said strand circuits, a test system for producing signals distinctive to various conditions of a tested line, and means under the control of apparatus at a calling sub-station during an established connection by one of said link connectors and operative previous to the response of a called sub-station to its calling signal, to eliminate said test system from the test contacts associated with both calling and called lines irrespective of the engagement of the contacts of said link connectors with the jack contacts of the calling and called lines by opening said talking and operating strand circuits of said link connector connected to the lines of both calling and called sub-stations.

51. A telephone exchange system, including telephone lines extending from sub-stations to a multiple switchboard, a link connector to connect called sub-stations to calling ones, a testing contact associated with a strand of said link connector, a test system which includes operating contacts associated with said lines and adapted to engage said testing contact when a test is made, a test circuit including different sources of variable current and said testing and operating contacts, means including a connection from one or more of said sources of variable current to said operating contacts, depending on the operating condition of a busy line, and a telephone receiver associated during a test with said test circuit, whereby said variable current is caused to produce an audible busy signal in said telephone receiver if the tested sub-station line is being signaled, an audible busy signal distinct in character from the first mentioned busy signal if said tested sub-station line is

being conversed upon or held for conversation, and an audible busy signal distinct in character from the two before mentioned busy signals if the tested sub-station line is being held for a sub-station waiting to be connected thereto.

52. A telephone exchange system, including telephone lines extending from sub-stations to a multiple switchboard, a link connector to connect called sub-stations to calling ones, a testing contact associated with a strand of said link connector, a test system which includes operating contacts associated with said lines and adapted to engage said testing contact when a test is made, a test circuit including different sources of variable current and said testing and operating contacts, means including a connection from one or more of said sources of variable current to said operating contacts, depending on the operating condition of a busy line, and an operator's and a calling sub-station's telephone receiver associated during a test with said test circuit, whereby said variable current is caused to produce an audible busy signal in said telephone receivers if the tested sub-station line is being signaled, an audible busy signal distinct in character from the first mentioned busy signal if the tested sub-station line is being conversed upon or held for conversation, and an audible busy signal distinct in character from the two before mentioned busy signals if the tested sub-station line is being held for a sub-station waiting to be connected thereto.

53. A telephone exchange system, including telephone lines extending from sub-stations to a multiple switchboard, link connectors to connect said sub-stations and comprising normally open separate talking and operating strand circuits individual to the respective link connectors for calling and called lines, means controlled by operators only for closing said strand circuits, a test system including means whereby a completed test circuit is caused to convey to said operator and a calling sub-station an audible busy signal if the tested sub-station line is being signaled, an audible busy signal distinct in character from the first mentioned busy signal if said tested sub-station line is being conversed upon or held for conversation, and an audible busy signal distinct in character from the two before mentioned busy signals if the tested sub-station line is being held for a sub-station waiting to be connected thereto.

54. A telephone exchange system, including telephone lines extending from sub-stations to a multiple switchboard having a test system which includes test thimbles or contacts of jacks, testing terminals of plugs adapted to be applied to said contacts of jacks before the plugs are plugged into said jacks, a test circuit which may include either

said contacts of jacks or contacts of plugs previously plugged into said jacks and engaging the test contacts thereof, the testing terminal of an applied testing plug, and a source of testing current, operator controlled means whereby a completed test circuit is caused to convey to said operator and a calling sub-station an audible busy signal if the tested sub-station line is being signaled, an audible busy signal distinct in character from the first mentioned busy signal if said tested sub-station line is being conversed upon or held for conversation, and an audible busy signal distinct in character from the two before mentioned busy signals if the tested sub-station line is being held for a sub-station waiting to be connected thereto.

55. A telephone exchange system, including telephone lines extending from sub-stations to a multiple switchboard having a test system which includes test thimbles or contacts of jacks, testing terminals of plugs adapted to be applied to said jack contacts before the plugs are plugged into said jacks, a test circuit which may include either jack test contacts or contacts of plugs previously plugged into said jacks and engaging the test contacts thereof, the testing terminal of an applied testing plug; different sources of continuous pulsating current in the operating circuits associated with the jack contacts used for making said tests; and operator controlled means whereby a completed test circuit is caused to convey to said operator and a calling sub-station an audible busy signal if the tested sub-station line is being signaled, an audible busy signal distinct in character from the first mentioned busy signal if the tested sub-station line is being conversed upon or is being held for conversation, and an audible busy signal distinct in character from the two before mentioned busy signals if the tested sub-station line is being held for a sub-station waiting to be connected thereto.

56. A telephone exchange system, including telephone lines extending from sub-stations to a multiple switchboard having in combination with relays for effecting switching operations a test system which includes test thimbles or contacts of jacks, testing terminals of plugs adapted to be applied to said jack contacts before the plugs are plugged into said jacks, a test circuit which may include either jack test contacts or contacts of plugs previously plugged into said jacks and engaging the test contacts thereof, the testing terminal of an applied testing plug, inductive windings of said relays and different sources of continuous pulsating current in the operating circuit associated with the jack contacts used for making said tests, and operator controlled means whereby a completed test circuit is caused to convey to said operator and a calling sub-station an audible busy signal if the tested sub-station line is being signaled, an audible busy signal distinct in character from the first mentioned busy signal if the tested sub-station line is being conversed upon or is being held for conversation, and an audible busy signal distinct in character from the two before mentioned busy signals if the tested sub-station line is being held for a sub-station waiting to be connected thereto.

dible busy signal if the tested sub-station line is being signaled, an audible busy signal distinct in character from the first mentioned busy signals if the tested sub-station line is being conversed upon or is being held for conversation, and an audible busy signal distinct in character from the two before mentioned busy signals if the tested sub-station line is being held for a sub-station 10 waiting to be connected thereto.

57. A telephone exchange system, including telephone lines extending from sub-stations to a multiple switchboard having a test system which includes test thimbles or 15 contacts of jacks, testing terminals of plugs adapted to be applied to said jack contacts before the plugs are plugged into said jacks, a test circuit which may include either jack test contacts or contacts of plugs previously 20 plugged into said jacks and engaging the test contacts thereof, the testing terminal of an applied testing plug, and a suitable source of testing current; operator controlled means whereby a completed test circuit 25 is caused to convey to said operator and a calling sub-station an audible busy signal if the tested sub-station line is being signaled, an audible busy signal distinct in character from the first mentioned audible 30 busy signal if the tested sub-station line is being conversed upon or held for conversation, and an audible busy signal distinct in character from the two before mentioned audible busy signals if the tested sub-station 35 line is being held for a sub-station waiting to be connected thereto, and means under the control of a sub-station for removing said source of testing current from the test thimbles or contacts of jacks associated with 40 its line, so that the line of said sub-station will test idle at any operator's position.

58. A telephone exchange system, including telephone lines extending from sub-stations to an exchange, line signaling apparatus at the exchange for said telephone lines, link connectors to connect said sub-stations and comprising normally open 45 separate talking and operating strand circuits individual to the respective link connectors for a calling and called line, means controlled by operators only for closing said talking and operating strand circuits during an established connection therewith, means governed by the closing of said strand 50 circuits for effacing the line signal of a calling line, and means governed by the sub-station apparatus of the calling line independently of the sub-station apparatus of the called line to open said talking and operating strand circuits of said link connector connected to its line thus removing their control over the line signal of the calling line and restoring same to the normal control 55 of said sub-station apparatus of the calling line.

line irrespective of the engagement of the 65 contacts of said link connector with jack contacts of the calling and called lines.

59. A telephone exchange system, including telephone lines extending from sub-stations to an exchange, line signaling apparatus at the exchange for said telephone lines, link connectors to connect said sub-stations and comprising normally open talking and operating strand circuits individual to the respective link connectors for a calling 75 and called line, means controlled by operators only for closing said talking and operating strand circuits, and means governed by the closing of said strand circuits for the effacing of the line signal of a called line, and means governed by the sub-station apparatus of the called line independent of the sub-station apparatus of the calling line to open said talking and operating strand circuits of said link connector connected to its 80 line thus removing their control over the line signal of the called line and restoring same to the normal control of said sub-station apparatus of the called line irrespective of the engagement of the contacts of said link connector with jack contacts of the calling and called lines.

60. A telephone exchange system, including telephone lines extending from sub-stations to an exchange, line signaling apparatus at the exchange for said telephone lines, link connectors to connect said sub-stations and comprising normally open 95 separate talking and operating strand circuits individual to the respective link connectors for a calling and called line, means controlled by operators only for closing said strand circuits and means governed by the closing of said strand circuits for the effacing of the line signal of a calling line, and means operative previous to the response of a called sub-station to its calling signal and governed by the substation apparatus of the calling line independent of the sub-station apparatus of the called line to open said talking and operating strand circuit, of said link to connector connected to both calling and called lines, thus removing their control over the line signals of both calling and called lines 10 and restoring same to the normal control of said sub-station apparatus of calling and called lines, irrespective of the engagement of the contacts of said link connector with jack contacts of the calling and called lines.

61. A telephone exchange system, including telephone lines extending from sub-stations to an exchange, link connectors for connecting said sub-stations, a supervisory relay for each link connector and adapted to 11 be connected in circuit with a talking strand thereof, and means to initially energize said relay by the full force of a current allowed

- to pass through its winding, and automatic means to continue the energization of said relay by a portion only of said current.
62. A telephone switchboard system including a link connector, a supervisory relay related thereto, a circuit closed by the engagement of the armature switch of said relay with its alternate contact, and means to maintain the closure of said circuit until 10 said armature switch after disengaging its alternate contact engages its normal contact.
63. A telephone switchboard system including a link connector, a supervisory relay related thereto, a circuit closed by the engagement of the armature switch of said relay with its alternate contact, and means to maintain the closure of said circuit until 15 said armature switch after disengaging its alternate contact engages its normal contact, and operator controlled means to close a circuit through the winding of said supervisory relay.
64. A telephone switchboard system including a link connector, a supervisory relay related thereto, a non-inductive resistance, and automatic means for bridging said resistance around the inductive winding of 20 said relay after its armature has been attracted.
65. A telephone switchboard system including a link connector, a supervisory relay related thereto, an answering relay, a circuit closed by the engagement of the 25 armature switch of said supervisory relay with its alternate contact and including the winding of said answering relay, a non-inductive resistance adapted to be bridged around the inductive winding of said supervisory relay by the operation of said 30 answering relay, said answering relay thereupon maintaining the closure of said circuit through its winding until the armature switch of said supervisory relay after disengaging said alternate contact engages its 35 normal contact, thereby shortcircuiting the winding of said answering relay and de-energizing the same.
66. A telephone switchboard system including a link connector, a supervisory relay related thereto, a calling relay, a circuit closed by the engagement of the armature switch of said supervisory relay with its 40 alternate contact and including the winding of said calling relay, a non-inductive resistance adapted to be bridged around the inductive winding of said supervisory relay by the actuation of said calling relay, said 45 calling relay thereupon maintaining the closure of said circuit through its winding until the armature switch of said supervisory relay after disengaging said alternate contact engages its normal contact, thereby shortcircuiting the winding of said 50 calling relay and de-energizing the same.
67. A telephone exchange system, including telephone lines extending from sub-stations to an exchange, calling signal apparatus at said sub-stations, a source of alternating current, a source of pulsating current whose pulsations alternate with the alternations of the alternating current from 70 said first mentioned source, a relay adapted to be included in circuit with said source of pulsating current but not with said source of alternating current, means operative when signaling a sub-station to connect said relay in circuit with said calling signal apparatus, said means also connecting said calling signal apparatus in circuit with said 75 source of alternating current, said calling signal apparatus being operative by said alternating current only and opaque to said pulsating current, whereby said relay is not actuated by said circuit, and means under the control of apparatus at said sub-station for closing a circuit thereat which is not opaque to said pulsating current, causing 80 thereby the instantaneous actuation of said relay.
68. A telephone exchange system including telephone lines extending from sub-stations to an exchange, calling signal apparatus at said sub-stations, a source of alternating current, a source of pulsating current whose pulsations alternate with the alternations of the alternating current from 85 said first mentioned source, and a source of continuous direct current, a relay, means to render said relay inoperative by said pulsating current when a circuit through a winding thereof is closed through said calling signal apparatus at one of said sub-stations, and means under the control of apparatus at said sub-station for closing a circuit 90 which causes the instant operation of said relay by said pulsating current, means whereby the operation of said relay substitutes said source of continuous direct current for said source of pulsating current to 95 maintain the actuation of said relay, telephonically connects the called sub-station to the telephone lines of a calling sub-station and permanently removes said source of alternating current from association with the 100 line of said called sub-station during an established connection between a calling and a called sub-station.
69. A telephone exchange system, including telephone lines extending from sub-stations to an exchange, calling signal apparatus at said sub-stations, link connectors to connect said sub-stations, a source of signaling current, a source of intermittent direct current, and a source of continuous direct current, a supervisory relay, a calling relay, and a ringing relay, associated with each of said link connectors, means to render said supervisory relay inoperative by 115 said intermittent direct current when a cir- 120
- 15 125 130

cuit through a winding thereof is closed through said calling signal apparatus at one of said sub-stations by means of one of said link connectors, and means under the control of apparatus at said sub-station for closing a circuit which causes the instant operation of said supervisory relay by said intermittent direct current, means whereby the operation of said supervisory relay energizes said calling relay substituting thereby said source of continuous direct current for said source of intermittent direct current to maintain the operation of said supervisory relay, telephonically connects the called sub-station to the telephone lines of a calling sub-station and deenergizes said ringing relay thereby permanently removing said source of signaling current from connection with said link connector during an established connection therewith, and means whereby the deenergization of said supervisory relay deenergizes said calling relay, the latter thereupon permanently opening the talking and operating strands of said link connector during an established connection therewith.

70. A telephone exchange system, including telephone lines extending from sub-stations to an exchange having link connectors to connect said sub-stations, a supervisory relay and an answering relay adapted to be associated with the line of a calling sub-station by means of one of said link connectors and under the control of apparatus at said sub-station, a supervisory relay and a calling relay adapted to be associated with the line of a called sub-station by means of said link connector and under the control of apparatus at said called sub-station, a supervisory signal energized by the actuation of said relays associated with the line of a calling sub-station, another supervisory signal energized by the actuation of said relays associated with the line of a called sub-station, and means under the control of apparatus at one connected sub-station to deenergize said relays associated with its line and consequently to deenergize said supervisory signal associated with its line, independently of the apparatus at the other sub-station, the deenergization of both said supervisory signals indicating the connection established by said link connector can be taken down.

55. 71. A telephone exchange system, including telephone lines extending from sub-stations to an exchange, link connectors to connect said sub-stations, operator controlled means to produce continuous calling signals at called sub-stations on the connection of a link connector with the line of a called sub-station, and automatic means to produce periodic calling signals at said called sub-station after said connection has been established.

72. A telephone exchange system, including telephone lines extending from sub-stations to an exchange, link connectors to connect said sub-stations, operator controlled means to produce continuous calling signals at called sub-stations on the connection of a link connector with the line of a called sub-station, and automatic means independent of said operator controlled means to produce periodic calling signals at said called sub-station after said connection has been established.

73. A telephone exchange system, including telephone lines extending from sub-stations to an exchange, link connectors to connect said sub-stations, a ringing relay and a finger contact operated relay for closing the talking and operating strand circuits of individual link connectors, operator controlled means including the magnetic windings of said relays to produce continuous calling signals at a called sub-station on the connection of a link connector with the line of said sub-station, and automatic means to produce periodic calling signals at said called sub-station after said connection has been established.

74. A telephone exchange system, including telephone lines extending from sub-stations to an exchange, link connectors to connect said sub-stations, a ringing relay and a relay for closing the talking and operating strand circuits of individual link connectors, operator controlled means whereby said relays are caused to produce continuous calling signals at a called sub-station on the connection of a link connector with the line of said sub-station, and produce periodic calling signals after said connection has been established.

75. A telephone exchange system, including telephone lines extending from sub-stations to an exchange, a link connector terminating in a calling plug, and a source of current for periodic signaling; in combination with a source of current for continuous signaling, and means to produce from said latter source a continuous calling signal at a called sub-station immediately upon the connection of said link connector with the line of said sub-station and thereafter automatically substitute periodic calling signals from the said first mentioned source, comprising a relay and manually controlled means for energizing the same, a ringing relay having a winding in the operating circuit of its associated link connector, said circuit being closed by said manually controlled relay after said calling plug has been connected to the line of a called sub-station, and means under the control of apparatus at a calling sub-station to maintain said circuit after closure, said relays acting jointly to connect the talking strands of said link connector to said source of current.

for continuous signaling, and the deenergization of said manually controlled relay causing the same to connect said talking strands of said link connector to said source of current for periodic signaling.

76. A telephone exchange system, including telephone lines extending from sub-stations to an exchange, a link connector terminating in a calling plug, and a source of

10 current for periodic signaling; in combination with a source of current for continuous signaling, and means to produce from said latter source a continuous calling signal at a sub-station immediately upon the connection

15 of a link connector with the line of said sub-station and thereafter automatically substitute periodic calling signals from the said first mentioned source, comprising a metallic thimble on said calling plug, a metallic

20 contact adapted to be worn on a finger of an operator, a finger contact relay individual to said link connector and having a winding in circuit with said thimble and contact, a ringing relay individual to said link connector

25 and having a winding in the operating circuit of its associated link connector, the operating circuit of said finger contact relay being closed by the engagement of said finger contact with the thimble of the calling

30 plug selected to make connection with a called sub-station whereby said finger contact relay is operated to close the circuit through the winding of the ringing relay to operate the same, and means under the control of a calling sub-station to maintain

35 said circuit after closure, said relays acting conjointly to connect the talking strands of said link connector to said source of current for continuous signaling, and the dis-

40 engagement of said finger contact from said thimble deenergizing said finger contact relay and causing the same to connect said talking strands of said link connector to said source of current for periodic signaling.

45 77. A telephone exchange system, including telephone lines extending from sub-stations to an exchange, link connectors to connect said sub-stations, operator controlled

50 means to produce continuous calling signals at called sub-stations on the connection of a link connector with the line of the called sub-station, and automatic means for producing periodic calling signals at said called

55 sub-stations after said connection has been established, and means for inductively producing an audible signal in the telephone receivers associated with the line of a calling sub-station when said calling signals are

60 transmitted to a called sub-station.

78. A telephone exchange system, including telephone lines extending from sub-stations to an exchange, link connectors to connect said sub-stations, operator controlled

65 means to produce continuous calling signals

at a called sub-station on the connection of a link connector with the line of the called sub-station, and automatic means to produce periodic calling signals at said called sub-station after said connection has been 70 established, and inductive means including a winding of a repeating coil, used for telephonically connecting said sub-station to a calling sub-station, in circuit with said sources of signaling current for producing 75 an audible signal in the telephone receivers associated with the line of said calling sub-station when said calling signals are transmitted to a called sub-station.

79. In combination, a source of alternating current, a source of direct current, instrumentalities adapted to be operated respectively by current from said sources, means for impressing alternating and direct current from said sources upon a circuit, 80 said direct current being impressed upon said circuit at intervals between alternations of said alternating current and then through instrumentalities other than those traversed by said alternating current, whereby the 85 alternating and direct current instrumentalities are energized depending on whether said circuit is closed by means opaque to one or the other of said currents, the periods of alternating and direct current impression 90 being of such frequency as to maintain the continuous operation of said instrumentalities adapted to be operated by said currents.

80. Central office commutating means for impressing alternating and direct current 100 upon a sub-station signaling circuit, said direct current being impressed upon said circuit at intervals between each of the alternations of said alternating current and then through the winding of a relay which 105 is not in circuit with said alternating current, whereby said relay is actuated according to whether the circuit at said sub-station is closed by means opaque to said direct current or not.

81. A telephone exchange system, including telephone lines extending from sub-stations to an exchange, a source of alternating current, a source of direct current, a relay, and a circuit including calling signal 115 apparatus at a sub-station, commutating means for impressing alternating and direct current from said sources upon said circuit, said calling signal apparatus being operative by said commutated alternating current and opaque to said commutated direct current, said commutated direct current being impressed upon said circuit at intervals between alternations of said commutated alternating current and then through a 120 winding of said relay which is not in circuit with said commutated alternating current, whereby said relay is actuated only when apparatus at said sub-station not opaque to said commutated direct current 125 130.

is substituted for said calling signal apparatus, the periods of commutated alternating and direct current impression being of such frequency as to maintain the continuous operation of said calling signal apparatus and said relay.

82. A telephone exchange system, including telephone lines extending from sub-stations to an exchange, a source of electric 10 energy, a supervisory relay, a circuit including calling signal apparatus at a sub-station and a circuit including the winding of said supervisory relay and controlled by means located at said sub-station, and commutation means for transmitting current to 15 said circuit including said calling signal apparatus at said sub-station to continuously operate the same and for transmitting current over the circuit controlled by 20 means at said sub-station and including the winding of said supervisory relay to instantly operate the latter, said commutating means adapted to transmit said current through said circuits at periods alternating 25 with each other and of such rapidity as not to impede said continuous operation of said calling signal apparatus or said instant operation of said supervisory relay, when said circuit under the control of said sub-station 30 is closed, and commutating means for automatically and periodically interrupting said commutated current delivered to said first mentioned circuit without interrupting said commutated current delivered to said last 35 mentioned circuit.

83. A telephone exchange system, including telephone lines extending from sub-stations having calling signal apparatus to an exchange having a source of alternating current, a source of direct current, a translating device, commutating means for transmitting current from said alternating current source to a sub-station line during a period represented by a part of an alternation 40 of said alternating current and current from said source of direct current through said translating device to said sub-station line at periods alternating with said periods of alternating current transmission, the calling 45 signal apparatus at the sub-station of said line being continuously operative by said commutated alternating current but inoperative by said commutated direct current, means under the control of an operator for connecting a sub-station line and its calling 50 signal apparatus in circuit with the alternating current commutating means, and means under the control of a party at a sub-station to complete the circuit of said sub-station 55 line through said direct current commutating means and said translating device, said device being inoperative by said commutated direct current when the circuit of said sub-station line is closed through said calling 60 signal apparatus, but operative thereby 65

which said circuit is closed by said sub-station controlled means.

84. A telephone exchange system, including telephone lines extending from sub-stations having calling signal apparatus to an exchange having a source of alternating current, a source of direct current, a supervisory relay, commutating means for transmitting current from said alternating current source to a sub-station line during a period represented by a part of an alternation of said alternating current and current from said source of direct current through the winding of said relay to said sub-station line at periods alternating with said periods of alternating current transmission, the calling signal apparatus at the sub-station of said line being continuously operative by said commutated alternating current but inoperative by said commutated direct current, means under the control of an operator for connecting a sub-station line and its calling signal apparatus in circuit with the alternating current commutating means, and means under the control of a party at a called sub-station to complete the circuit of said sub-station line through said direct current commutating means and the winding of said supervisory relay, said relay being inoperative by said commutated direct current when the circuit of said sub-station line is closed by an operator through said calling 70 75 80 85 90 95 100 105 110 115 120 125 130

85. A telephone exchange system, including telephone lines extending from sub-stations having calling signal apparatus to an exchange having a source of alternating current, a source of direct current, a relay, commutating means for transmitting current from said alternating current source to a sub-station line during a period represented by the apex of a semi-cycle of said alternating current and current from said source of direct current through the winding of said relay to said sub-station line at periods alternating with said periods of alternating current transmission, the calling signal apparatus at the sub-station of said line being continuously operative by said commutated alternating current but inoperative by said commutated direct current, means under the control of an operator for connecting a sub-station line and its calling signal apparatus in circuit with the alternating current commutating means, and means under the control of a party at a called sub-station to complete the circuit of said sub-station line through the direct current commutating means and the winding of said supervisory relay, said relay being inoperative by said commutated direct current when the circuit of said sub-station line is closed by an operator through said calling 100 105 110 115 120 125 130

signal apparatus, but operative thereby when said circuit is closed by said sub-station controlled means.

86. A telephone exchange system, including telephone lines extending from sub-stations having calling signal apparatus to an exchange having a source of alternating current, a source of direct current, a supervisory relay, and commutating means for transmitting current from said alternating current source to a sub-station line during a period represented by a part of an alternation of said alternating current and current from said source of direct current through the winding of said relay to said sub-station line at periods alternating with said periods of alternating current transmission, the calling signal apparatus at the sub-station of said line being continuously operative by said commutated alternating current but inoperative by said commutated direct current, commutating means for automatically and periodically interrupting said commutated alternating current without interrupting said commutated direct current, means under the control of an operator for connecting a sub-station line and its calling signal apparatus in circuit with said alternating current commutating means, and means under the control of a party at a called sub-station to complete the circuit of said sub-station line through the direct current commutating means and the winding of said supervisory relay, said relay being inoperative by said commutated direct current when the circuit of said sub-station line is closed through said calling signal apparatus but operative thereby when said circuit is closed by said sub-station controlled means.

87. A telephone exchange system, including telephone lines extending from sub-stations to an exchange including relays and induction coils the primaries of which are in circuit with said relays, and commutating means for producing a continuous pulsating current adapted to actuate said relays and maintain their actuation without vibrating their armatures and at the same time energize the primaries of said induction coils in such a way that the secondaries thereof will cause an audible telephonic signal to be sounded.

88. A telephone exchange system, including telephone lines extending from sub-stations to an exchange including relays and induction coils the primaries of which are in circuit with said relays, and commutating means adapted to intermittently include a resistance in said circuit for producing a continuous pulsating current adapted to actuate said relays and maintain their actuation without vibrating their armatures, and at the same time energize said primaries of said induction coils in such a way that the

secondaries thereof will cause an audible telephonic signal to be sounded.

89. A telephone exchange system, including telephone lines extending from sub-stations to a multiple switchboard, link connectors to connect said sub-stations, relays associated with said link connectors, commutating means for producing a continuous pulsating current, a circuit including said commutating means and one or more of said relays, said continuous pulsating current adapted to actuate said relays and maintain them actuated without vibrating their armatures and at the same time affect a telephone receiver, associated with said circuit when making busy tests on called for lines, in such a way that an audible signal is sounded in said telephone receiver.

90. A telephone exchange system, including telephone lines extending from sub-stations to a multiple switchboard, link connectors to connect said sub-stations, relays associated with said link connectors, commutating means for producing a continuous pulsating current, a circuit including said commutating means and one or more of said relays, said continuous pulsating current adapted to actuate said relays and maintain them actuated without vibrating their armatures and also affect a calling sub-station's and an operator's telephone receiver, associated with said circuit when making busy tests on called for lines, in such a way that an audible signal is sounded in said telephone receivers.

91. A telephone exchange system, including telephone lines extending from sub-stations to a multiple switchboard, link connectors terminating in answering and calling plugs to connect said sub-stations, a ringing relay, a source of signaling current, means to automatically prevent the actuation of said ringing relay when a calling plug associated with one of said link connectors connected to a calling line is plugged into a jack connected to a busy line, thus preventing the transmission of a calling signal from said source of signaling current to said busy line, and means under the control of apparatus at said busy sub-station to actuate said ringing relay, the latter transmitting said calling signal to said sub-station, said calling sub-station being completely disconnected from said called sub-station until said ringing relay has actuated.

92. A telephone exchange system, including telephone lines extending from sub-stations to a multiple switchboard, link connectors terminating in answering and calling plugs to connect said sub-stations, a waiting relay, a ringing relay and a calling relay, a source of periodic signaling current and a source of continuous signaling current, means including said waiting relay to automatically prevent the actuation of said ring-

- ing relay and to change the signaling circuit controlled by said relay from said source of periodic signaling current to said source of continuous signaling current when
- 5 a calling plug associated with one of said link connectors connected to a calling line is plugged into a jack connected to a busy line, thus preventing the transmission of a calling signal to said busy line, and means
- 10 under the control of apparatus at said busy sub-station to actuate said ringing relay, the latter, in conjunction with said waiting relay previously actuated, instantaneously transmitting said calling signal to said sub-
- 15 station, and means also under the control of apparatus at said sub-station, but only after the transmission of said calling signal, to actuate said calling relay and thereby telephonically connect said sub-station to said
- 20 calling line, said calling line being completely disconnected from said called sub-station until said ringing relay has actuated.
93. A telephone exchange system, including telephone lines extending from sub-stations to a multiple switchboard, link connectors comprising separate talking and operating strand circuits individual to the respective link connectors for calling and called lines, a source of signaling current for
- 25 operating calling signal apparatus at said sub-stations, means whereby the line of a calling sub-station can be connected by one of said link connectors to the line of a busy sub-station, said talking and operating
- 30 strand circuits associated with the line of the calling sub-station being closed by means associated with said operating strand circuit, and said talking strand circuit associated with the line of said busy sub-station
- 35 remaining open and said operating strand circuit associated with the line of said busy sub-station being closed by means associated with said operating strand circuit, means under the control of apparatus at said busy
- 40 sub-station to release its line from telephonic connection with the sub-station to which it has been connected and connect said talking strand circuit associated with its line to said source of signaling current, said
- 45 means including means associated with said operating strand circuit whereby said calling signal apparatus at said sub-station previously busy is operated, means associated with said operating strand circuit and also
- 50 under the control of apparatus at said sub-station previously busy whereby said sub-station is telephonically connected to said calling sub-station and said signaling current is permanently removed from its lines
- 55 during an established connection.
94. A telephone exchange system, including telephone lines extending from sub-stations to a multiple switchboard, link connectors comprising separate talking and operating strand circuits individual to the re-
- spective link connectors for calling and called sub-stations, a source of periodic signaling current and a source of continuous signaling current for operating calling signal apparatus at said sub-stations, an answering relay, a waiting relay, a ringing relay, and a calling relay, means including said waiting relay and said ringing relay whereby the line of a calling sub-station can be connected by one of said link connectors to the line of a busy sub-station, said talking and operating strand circuits associated with the line of the calling sub-station being closed by the actuation of said answering relay, said talking strand circuit associated with the line of said busy sub-station remaining open by the non-actuation of said ringing relay and said operating strand circuit associated with the line of said busy sub-station being closed by the actuation of said waiting relay, means under the control of apparatus at said busy sub-station to release its line from telephonic connection with the sub-station to which it has been connected and close said talking strand circuit associated with its line by the immediate actuation of said ringing relay due to said release, the previous actuation of said waiting relay changing the signaling circuit controlled by said ringing relay from said source of periodic signaling current to said source of continuous signaling current, whereby said calling signal apparatus at said sub-station previously busy is instantaneously operated, means also under the control of apparatus at said sub-station previously busy and including said calling relay whereby said sub-station is telephonically connected to said calling sub-station, said signaling current being permanently removed from its line during an established connection, by the deenergization of said waiting and ringing relays caused by the actuation of said calling relay.
95. A telephone exchange system, including telephone lines extending from sub-stations to a multiple switchboard, a source of continuous signaling current and a source of periodic signaling current for actuating calling signal apparatus at said sub-stations, a waiting relay the actuation of which substitutes said source of continuous signaling current for said source of periodic signaling current in a circuit connected to said calling signal apparatus, a ringing relay for transmitting said signaling currents to a called sub-station, said ringing relay being inoperative when associated with a busy line but in series with said waiting relay which is operative when so associated with a busy line, said ringing relay being operative when associated with an idle line, thereby short-circuiting the winding of said waiting relay by operator controlled means essential to establish a connection with said line, thus removing said waiting relay from

said circuit, and said ringing relay being operative when associated with a busy line when latter becomes idle without short-circuiting said winding of said waiting relay.

5 96. A telephone exchange system, including telephone lines extending from sub-stations to an exchange, link connectors to connect said sub-stations in combination with automatic means to prevent a waiting telephonic connection between any calling sub-station and a busy sub-station with which a waiting connection has already been made.

10 97. A telephone exchange system, including telephone lines extending from sub-stations to a multiple switchboard, link connectors to connect said sub-stations and comprising separate talking and operating strands for calling and called lines, a relay associated with the calling line operating 15 strand of each of said link connectors, the actuation of said relay being essential to establish a telephonic connection between two sub-stations, talking and operating contacts associated with each of said telephone lines 20 adapted to be connected respectively to said talking and operating strands, a source of electrical energy, means to close a circuit through said source and a winding of said relay, said circuit including a separate limb 25 for each telephone line from one pole of said source to said contacts and said limb of such resistance as to allow the passage of sufficient current to actuate said relay only when current is not passing from said contacts to instrumentalities used in establishing a telephonic connection pertaining to another link connector, whereby the telephonic connection of a sub-station to a busy 30 sub-station by means of the calling line link connector strands is automatically prevented.

35 98. A telephone exchange system, including telephone lines extending from sub-stations to a multiple switchboard, link connectors to connect said sub-stations and comprising separate talking and operating strands terminating in answering and calling plugs, a manually controlled relay associated with each operating strand terminating 40 in said answering plug of said link connectors, the actuation of said relay being essential to establish a telephonic connection between sub-stations, multiple jacks associated with each of said telephone lines, an operating contact for each of said jacks adapted to engage a contact on said plug connected to said operating strand, a source of electrical energy, means to close a circuit through said source and a winding of 45 said relay, said circuit including a separate limb for each telephone line from one pole of said source to said operating contacts, said limb being of such resistance as to allow the passage of sufficient current to actuate said relay only when current is not passing from said operating contacts to instrumentalities used in establishing a telephonic connection pertaining to another link connector, whereby the 50

passing from said operating contacts to instrumentalities used in establishing a telephonic connection pertaining to another link connector, whereby the telephonic connection of a sub-station to a busy sub-station, by means of the engagement of said answering plug with one of said jacks associated with the telephone line of said busy sub-station, is automatically prevented.

55 99. A telephone exchange system, including telephone lines extending from sub-stations to a multiple switchboard, link connectors to connect said sub-stations and comprising separate talking and operating strands for calling and called lines, a relay 60 associated with the called line operating strand of each of said link connectors, the actuation of said relay being essential to establish a telephonic connection between sub-stations, talking and operating contacts 65 associated with each of said telephone lines adapted to be connected respectively to said talking and operating strands, a source of electrical energy, means to close a circuit through said source and a winding of said 70 relay, said circuit including a separate limb for each telephone line from one pole of said source to said contacts and said limb of such resistance as to allow the passage of sufficient current to actuate said relay only 75 when current is not passing from said contacts to instrumentalities used in establishing a telephonic connection pertaining to another link connector, whereby the telephonic connection of a sub-station to a busy 80 sub-station by means of the called line link connector strands is automatically prevented.

85 100. A telephone exchange system, including telephone lines extending from sub-stations to a multiple switchboard, link connectors to connect said sub-stations and comprising separate talking and operating strands terminating in answering and calling plugs, a ringing relay associated with 105 each operating strand terminating in said calling plug of said link connectors, the actuation of said relay being essential to establish a telephonic connection between sub-stations, multiple jacks associated with 110 each of said telephone lines, an operating contact for each of said jacks adapted to engage a contact on said plug connected to said operating strand, a source of electrical energy, means to close a circuit through said 115 source and a winding of said relay, said circuit including a separate limb for each telephone line from one pole of said source to said operating contacts, said limb being of such resistance as to allow the passage of sufficient current to actuate said relay only 120 when current is not passing from said operating contacts to instrumentalities used in establishing a telephonic connection pertaining to another link connector, whereby the 125 130

telephonic connection of a sub-station to a busy sub-station, by means of the engagement of said calling plug with one of said jacks associated with the telephone line of said busy sub-station, is automatically prevented.

101. A telephone exchange system, including telephone lines extending from sub-stations to a multiple switchboard, an operator's set, link connectors to connect said sub-stations and comprising separate talking and operating strands for calling and called lines, a relay associated with the calling line operating strand of each of said link connectors, the actuation of said relay being essential to establish a telephonic connection between a sub-station and said operator's set, talking and operating contacts associated with each of said telephone lines adapted to be connected respectively to said talking and operating strands, a source of electrical energy, means to close a circuit through said source and a winding of said relay, said circuit including a separate limb for each telephone line from one pole of said source to said contacts and said limb of such resistance as to allow the passage of sufficient current to actuate said relay only when current is not passing from said contacts to instrumentalities used in establishing a telephonic connection pertaining to another link connector, whereby the telephonic connection of said operator's set to a busy sub-station, by means of the calling line link connector strands, is automatically prevented.
102. A telephone exchange system, including telephone lines extending from sub-stations to a multiple switchboard, an operator's telephone set, link connectors to connect said sub-stations and comprising separate talking and operating strands terminating in answering and calling plugs, a manually controlled relay associated with each operating strand terminating in said answering plug of each of said link connectors, the actuation of said relay being essential to establish a telephonic connection between a sub-station and said operator's telephone set, multiple jacks associated with each of said telephone lines, an operating contact for each of said jacks adapted to engage a contact on said plug connected to said operating strand, a source of electrical energy, means to close a circuit through said source and a winding of said relay, said circuit including a separate limb for each telephone line from one pole of said source to said operating contacts, said limb being of such resistance as to allow the passage of sufficient current to actuate said relay only when current is not passing from said operating contacts to instrumentalities used in establishing a telephonic connection pertaining to another link connector, whereby the telephonic connection of said operator's

telephone set to a busy sub-station, by means of the engagement of said answering plug with one of said jacks associated with the telephone line of said busy sub-station, is automatically prevented.

103. A telephone exchange system, including telephone lines extending from sub-stations to a multiple switchboard, an operator's telephone set, link connectors to connect said sub-stations and comprising separate talking and operating strands for calling and called lines, a relay associated with the calling line operating strand of each of said link connectors, the energization of said relay being essential to establish a telephonic connection between a sub-station and said operator's telephone set, a relay associated with the called line operating strand of each of said link connectors, the actuation of said relay being essential to establish a telephonic connection between a calling and a called sub-station, said actuation opening the circuit through said first mentioned relay, whereby the telephonic connection of said operator's telephone set to a sub-station line telephonically connected to another sub-station is automatically prevented.

104. A telephone exchange system, including telephone lines extending from sub-stations to a multiple switchboard, an operator's telephone set, link connectors to connect said sub-stations and comprising separate talking and operating strands for calling and called lines, a manually controlled relay associated with the calling line operating strand of each of said link connectors, the energization of said relay being essential to establish a telephonic connection between a sub-station and said operator's telephone set, a calling relay associated with the called line operating strand of each of said link connectors, the actuation of said calling relay being essential to establish a telephonic connection between a calling and a called sub-station, said actuation opening the circuit through said first mentioned relay, whereby the telephonic connection of said operator's telephone set to a sub-station line telephonically connected to another sub-station line is automatically prevented.

105. A telephone exchange system, including telephone lines extending from sub-stations to a multiple switchboard, link connectors to connect said sub-stations and comprising separate talking and operating strands terminating in answering and calling plugs, a waiting relay associated with each operating strand terminating in said calling plug of said link connectors, the actuation of said relay being essential to establish a waiting connection between a calling sub-station and a busy sub-station, multiple jacks associated with each of said telephone lines, an operating contact for

each of said jacks adapted to engage a contact on said plugs connected to said operating strand, a source of electrical energy, means to close a circuit through said source and a winding of said relay, said circuit including a separate limb for each telephone line from one pole of said source to said operating contacts, and said limb of such resistance as to allow the passage of sufficient current to actuate said relay only when current is not passing from said operating contacts to a waiting relay used in es-

tablishing a waiting connection pertaining to another link connector, whereby the waiting connection of a sub-station to a busy sub-station with which a waiting connection has already been made is automatically prevented.

In witness whereof, I hereunto subscribe my name this 20th day of June, A. D. 1914.

HUBERT S. TURNER.
